ABSTRACT

A labeling machine having primary and secondary label feed assemblies provided in the present labeler with a common source of intermittent power for feeding labels that can be selected to actuate either assembly from a reciprocating power driven member through over-running clutches to give a positive label feeding movement without and to prevent backlash to the label pack supporting and feeding elements. The assemblies may operate independently of each other or/and in an interdependent manner to maintain the top or operating label pickup level of the label pack at a substantially constant operating level. With the present label feed mechanism the operating of the labeler may be continuous without the necessity to stop the labeling operation when introducing a fresh pack of labels to the machine. The primary label pack feeding mechanism stops automatically upon the exhaustion of the labels of the pack. The secondary label pack feeding mechanism also stops automatically upon reaching a predetermined feeding height rather than to a point of complete exhaustion of its respective labels or label pack to prevent breakdown clashing between the primary and secondary feeding mechanisms.

LABELLING MACHINE

The present divisional application is a division of the present applicant's original patent application on Labeling Machine, filed Dec. 28, 1966, Ser. No. 605,279, issued Mar. 14, 1972, U.S. Pat. No. 3,648,823.

The present invention relates to a machine for labeling cans and other cylindrical type packages that are passed through the machine between guide bars by a rolling operation in a horizontal path and direction, passing in turn over a glue or heavy adhesive applying mechanism for the initial label pickup, thence over a label pack and paste or light adhesive label pasting mechanism, thence over a label pressing pad to the discharge end of the machine. In this operation the glue or heavy adhesive is first applied to the cans or packages, the labels are then picked up in turn by the heavy adhesive on the cans or packages and rolled about the same, the light adhesive or paste is then applied to the opposite or lap end of each of the labels in a successive manner. These paste treated label lap ends are successively brought into engaged pasted contact with the cans or to the opposite ends of the labels forming a lap type of joint as they pass over the paste mechanism and then finally pressed into close contact with the cylindrical walls of the cans or packages and thereafter delivered from the machine. This general type of machine is shown in the patent to Clifford H. Neer, U.S. Pat. No. 2,185,947, dated Jan. 2, 1940 and also the patent to Victor H. Henthorn, U.S. Pat. No. 2,804,303 dated Aug. 27, 1957, and C. H. Wild, U. S. Pat. No. 1,627,946 dated May 10, 1927.

In general, these machines are provided with a pair of power driven horizontal belts which contact the upper sides or beading of the containers and rolls them between guide bars through the machine. Located below the bed of the machine over which the containers roll is a pack of labels supported adjacent the bed and in a position so that when a container passes over the pack of labels the heavy adhesive or glue which has been previously picked up by the rolling container, comes in contact with the near end of the top of the label pack, picking up the near end of the uppermost label; the opposite or far end of the label having had paste applied thereto by the triggering action on the paste mechanism by the preceding can; which is then pulled out from under the label curling bar and then wrapped and secured about the cylindrical container by the overlapping of the opposite ends of the label forming a pasted lap joint. As the labels are picked off the top of the pack by the containers the remaining labels are fed, or pushed upwardly towards the bed in order that the successive containers will also pick up corresponding labels. It is with this type of machine that the present improvements are identified.

These improvements relate to a single belt for conveying the cans through the machine, its novel adjustable supports, elbow drive and associated parts adaptable to different sized cans, a heavy adhesive or glue pot having combined novel means of support and adjustment for different sized cans, together with a modified form of glue pot having novel fountain means for applying glue to the side walls of the cans; improved forms of label pack feeding mechanisms as identified with both primary and secondary means for feeding label packs and their labels together with their respective controls; novel means for adjusting the can guides,

5 a light adhesive or paste pot having a paste belt for applying paste to the labels with novel means for scraping and controlling the amount of working paste carried by the belt to be introduced to the label together with novel self tensioning means for the paste belt and secondary or auxiliary supporting means for the activated label pack having novel means to maintain the supporting means in variable operative feeding positions.

An object of the present invention is to provide the 10 present machine with a single can conveyor belt that engages the side walls of the cans for the full width of the belt, rather than two belts where each belt engages only the narrow beading at the opposite ends of the can, thereby engaging the can over a much larger area 15 to prevent slippage and cocking of the can to increase the positive effectiveness of the conveyor operation and in view of the belt engaging and pressing the label against the wall of the can for a greater portion of the run the label is caused to have a tighter engagement 20 with the can.

Another object of the present invention is to provide the machine with a heated adjustable glue pot, for a 25 heavy quick acting adhesive, that is supported in such a manner as to have a minimum of heat losses, using less current for maintaining the pot at a predetermined operating temperature and to comparatively reduce the time for preheating the pot preparatory to initial operation.

30 An important object of the present invention is to provide improved primary and secondary label pack feeding mechanisms that may operate independently of each other or in an interdependent manner to maintain the top or operating pickup level of the label pack at 35 a substantially constant operating level, the secondary label pack providing feeding means for eliminating the necessity of stopping the labeling operation for replenishing the labels or packs as is required when only a single type of label pack feeding mechanism is used, and 40 also to provide the said feeding mechanisms with highly sensitive means for response to a minimal variation of a few labels at the top operating level of the pack as to cause either or both of said mechanisms to either start or stop feeding labels or the label pack and also means 45 to provide a very positive feeding action with no backlash and with little or no comparative wear, and also to provide means for readily raising and lowering the feed mechanisms by hand and means for readily engaging and disengaging the same from its power source by 50 hand.

55 A further object of the present invention is to provide means for automatically stopping the primary feed mechanism identified with the primary label pack supporting table upon the exhaustion of the labels from the table and further means for automatically stopping the secondary feed mechanism identified with the secondary label pack supporting arms and their attendant pack engaging elements upon the arms and their elements being fed to a predetermined height.

60 Another object of the invention is to provide the present machine with a paste conveying belt for applying paste to the lap ends of the labels having novel means to maintain the belt under constant predetermined tension and also a novel form of belt scraper for the belt having means to adjustably control the amount of paste conveyed by the belt and means to prevent the 65 adjustable control from freezing or becoming stuck due

to the paste about the control drying out and becoming hard.

With these and other objects in view, other important features of the machine will be discussed and those referred to above will be further discussed in connection with the accompanying drawings.

In the drawings a machine embodying the features of the invention in their preferred form is illustrated.

In the drawings:

FIG. 1 is an assembly view of a front elevation of the feed half of the labelling machine.

FIG. 2 is a front elevational view and a continuation of FIG. 1 of the delivery end of the labelling machine.

FIG. 3 is a fragmentary rear elevational view of the feed end of the machine illustrating particularly the elevating mechanism for the can feed belt and pulley assembly at this end of the machine.

FIG. 4 is a similar view to FIG. 3 showing a rear fragmentary elevation of the discharge end of the machine and illustrating the elevating and driving mechanism for the can feed belt and its pulley assembly at this end of the machine.

FIG. 5 is a detailed fragmentary view shown in elevation of the adjustment hand wheel assembly for controlling the speed of the motor drive belt of the machine and is somewhat of a continuation of this element as identified with FIG. 4.

FIG. 6 is a fragmentary elevational view shown partly in section illustrating the primary or main supporting table for the label pack and its yielding supporting mechanism together with one of the secondary or auxiliary label pack supporting arms and its yielding supporting mechanism.

FIG. 7 is a continuation of FIG. 6 showing a fragmentary elevational view partly in section, illustrating the intermittent paste belt depressor together with the label curling bar assembly.

FIG. 8 is a fragmentary elevational view partly in section of the paste pot and its paste belt wiping assembly.

FIG. 9 is a fragmentary transverse sectional view through the machine partly in section looking towards the feed end, illustrating the can guide supporting arms and the adjustable supporting brackets for the label guides and the adjustable elements for adapting the primary or main label pack supporting table and the secondary or auxiliary label pack supporting arms to different width labels.

FIG. 10 is a fragmentary plan view of the can feed end of the machine.

FIG. 11 is a similar plan view to FIG. 10 and is a continuation thereof.

FIG. 12 is a similar plan view to FIG. 11 and is a continuation thereof.

FIG. 13 is a similar fragmentary plan view of the delivery end of the machine and is a continuation of FIG. 12.

FIG. 14 is a fragmentary plan view shown partly in section of the readily disengageable clutch mechanism between the removable paste pot and its driving mechanism.

FIG. 15 is a fragmentary elevational view of the clutch face of the glue pot as shown in FIG. 14.

FIG. 16 is a fragmentary plan view of the center portion of the machine taken in the area of the screw adjusting brackets for the primary label pack supporting

table and also the secondary label pack supporting arms for adjusting the table and arms to different widths of labels.

FIG. 17 is a cross sectional view taken on the line 17-17 of FIG. 16 illustrating one of the adjustable knife edges for retaining pressure on the top edges of the label pack.

FIG. 18 is a fragmentary transverse sectional view looking towards the discharge end of the machine illustrating the screw adjusted follower brackets and their elements for adjusting the width of the primary label pack table.

FIG. 19 is a fragmentary view of the dual adjusting knob and handle for applying transverse movement to each of the adjusting screws and their respective assemblies or to the respective follower brackets mounted on the screw members.

FIG. 20 is a cross sectional view taken on the line 20-20 of FIG. 19.

FIG. 21 is a front fragmentary elevational view partly in section of the adjustable paste belt wiping head.

FIG. 22 is an enlarged fragmentary sectional view of a side elevation of the lower portion of the paste belt wiping head.

FIG. 23 is an inverted fragmentary plan of the paste belt wiping head.

FIG. 24 is a fragmentary plan of the paste belt illustrating a strip of paste as applied thereto by the head as shown in FIG. 22.

FIG. 25 is a cross sectional view taken on the line 25-25 of FIG. 24.

FIG. 26 is a detailed fragmentary plan view partly in section of the elbow type sprocket drive for the can feed belt pulley as shown in FIG. 4.

FIG. 27 is a fragmentary elevational view partly in section illustrating the means for moving and adjusting the can guides to particular sized cans.

FIG. 28 is a fragmentary elevational view partly in section looking towards the discharge end of the machine illustrating the can track screw adjusting brackets together with the intermittent paste belt depressors and the adjusting guides for the labels.

FIG. 29 is a fragmentary side elevational view looking toward the discharge end of the machine illustrating the dual type of constant tensioning head for the paste belt retaining and tensioning pulleys.

FIG. 30 is a side elevational view looking in the direction of the feed end of the machine of the glue pot shown partly broken away illustrating the glue conveyor wheels and their gear drive together with a can at the moment of glue pickup from the wheels.

FIG. 31 is a fragmentary elevational view looking in the direction of the discharge end of the machine, illustrating the reverse side and the lower part of the glue pot with its supporting racks and bearings together with the rack engaging adjusting pinions for positioning the glue pot.

FIG. 32 is a fragmentary front elevational view of the lower part of the glue pot with its front cover plate removed disclosing the heating element for the glue pot.

FIG. 33 is a cross sectional view taken on the line 33-33 of FIG. 30.

FIG. 34 is a fragmentary cross sectional view taken on the line 34-34 of FIG. 31.

FIG. 35 is a fragmentary elevational view illustrating the adjustable supporting bracket for the pair of glue

pot supporting racks positioned between the vertical frame members at the feed end of the machine.

FIG. 36 is a fragmentary elevational view looking in the direction of the delivery end of the machine illustrating the adjustable supporting bracket for the opposite ends of the glue pot supporting racks.

FIG. 37 is a fragmentary cross sectional view taken on the line 37—37 of FIG. 35.

FIG. 38 is a fragmentary elevational view taken from the rear of the machine showing the rack and pinion actuating mechanisms for feeding the primary label pack table and secondary label pack supporting arms.

FIG. 39 is a fragmentary elevational view of one of the over-running clutches and its respective actuating arm as used in both the primary label pack feed and the secondary label pack feeding mechanism.

FIG. 40 is a fragmentary sectional plan view looking from the rear of the machine and in the same relative position as that shown for FIG. 38 illustrating portions of the actuating mechanism for both the primary label pack table feed and the feed for the secondary label pack support with their respective feeding mechanisms together with the respective hand operated engaging and disengaging clutch mechanism for both the respective feeds.

FIG. 41 is a fragmentary cross sectional view taken on the line 41—41 of FIG. 40 looking in the direction of the arrows.

FIG. 42 is a fragmentary end elevational view partly in section of the primary label pack table feed mechanism looking in the direction of the feed end of the machine.

FIG. 43 is a fragmentary end elevational view partly in section of the feed mechanism for the secondary label pack supporting elements, looking towards the feed end of the machine.

FIG. 44 is a fragmentary side elevational view partly broken away for the illustrative purpose of showing one of the over-running clutches and its actuating arm similar to that shown in FIG. 39.

FIG. 45 is a fragmentary side elevational view looking in the direction of the discharge end of the machine of the locking mechanism for fixedly positioning the elevating assembly for the adjusted position of the can feed belt and its respective supporting and driving pulleys, together with a fragmentary showing of one of the adjustable supporting arms for one of the can guides.

FIG. 46 is a sectional view on the line 46—46 of FIG. 45.

FIG. 47 is a plan view of a modified form of glue pot adapted to operate in the present labelling machine and being provided with a plurality of selective pressure controlled fountain type glue dispensing fingers for introducing glue to the over-running can.

FIG. 48 is a cross sectional view taken on the line 48—48 of FIG. 47.

FIG. 49 is a fragmentary view partly in section of the glue pickup cylinder as shown in FIG. 48 together with a part sectional detail of one of the fountain finger glue dispensing members and its tension means for controlling the flow of glue from its respective outlet.

FIG. 50 is a fragmentary plan view of the frictional drive mechanism as identified with the drive end portion of the modified form of fountain finger glue pot shown in FIG. 47.

FIG. 51 is an end elevational view of friction drive assembly for the modified form of glue pot as shown in FIG. 50.

FIG. 52 is a cross sectional view taken on the line 52—52 of FIG. 50.

FIG. 53 is an end elevational view in cross section taken on the line 53—53 of FIG. 50.

FIG. 54 is a fragmentary elevational view partly in section and somewhat diagrammatic, showing a portion 10 of the label feed control mechanism with its latch member in locked position.

FIG. 55 is a fragmentary elevational view partly in section illustrating the initial can tripping elements for controlling the label feed mechanisms of both the primary and secondary label feeds.

FIG. 56 is an enlarged fragmentary elevational view of one of the label hold down knives and its clamping assembly as seen in FIG. 6 on a very small scale.

Referring to the drawings by reference numerals 20 each of which designates the same or similar parts throughout the different figures and with particular reference to FIGS. 1 and 2 the machine comprises an upper longitudinal frame member 1 located on the far side and running the full length of the machine, and two 25 near side separated frame members 2 and 2' running parallel and on a plane with the frame member 1, these frame members provide supporting means for the various runways for the containers and certain other elements of the machine to be hereinafter described. A pair of lower parallel horizontal frame members 3 running substantially the full length of the machine provides supporting means for the primary and secondary label pack feeding mechanisms 4 and 5 respectively and their respective upper primary and secondary label 30 pack supporting assemblies 6 and 7, and also providing a support for the motor drive assembly 8. The upper and lower horizontal frame members are connected and held in spaced relation by two pairs of upright frame members 9 and 10 at the feed and delivery ends of the machine respectively. These uprights also support operating elements of the machine. For purposes of supporting the machine proper it is provided with a lower pedestal 11 comprising the usual leg, brace and base structures.

45 For purposes of conveying the cans or containers through the machine a single conveyor or can feed belt 12 is provided, supported on power driven and idler pulleys 13 and 14, respectively, the belt running substantially the full length of the center of the machine and having a pair of counteracting adjustable pulleys 15 for taking up slack in the top run of the belt and suitably supported on the horizontal bar member 17 by bracket 16 as shown. The opposite ends 18 and 18' of this bar are rigidly supported by the respective pulley assembly brackets or overhanging extensions 19 and 20 and are raised or lowered in a unified manner with the can feed belt pulleys when these members are vertically moved to an adjusted height best suited for the conveyor belt's engagement with containers of a particular size. The bar 17 provides a support for two groups 21 and 21' of conveyor belt pressure rollers 22 and 22' and their respective supporting brackets 23 and 23' fixedly attached to the bar 17 as shown. The belt pressure rollers of each group are directly supported on the free ends of the pivoted horizontal arms 24 and 24' which in turn are supported by their respective bar bracket members as shown. Each of the said bracket 50 55 60 65 65

and arm assemblies of the respective groups are provided with compression spring members 25 and 25' positioned between the bracket and arm structures as shown for purposes of providing resilient and yielding pressure through their respective roller members to the lower run of the conveyor belt. The respective arms and brackets of each group are provided with opposing stop elements 26 and 26' as shown for purposes of limiting the downward movement and position of the horizontal arms and their belt engaging rollers to prevent unnecessary drag on the belt.

The container runway of the machine proper from the feed end 27 to the area or point 28 of the initial label pickup by the container is on a slightly lower level than the remaining portion of the runway to the delivery end of the machine. To compensate for this difference the rollers 22 of group 21 are somewhat proportionally larger in diameter whereby the conveyor belt function identified with this lower level will be uniform and positive in action as to the feeding engagement of the belt with the cans or containers. This positive feeding of the containers in this area without slippage is important in that the point of initial application of glue or heavy adhesive to the side wall of the can or container during its rolling action past the glue applying wheels 29 of the glue pot 30 must register in proper alignment with the pickup end of the top label of the pack. In this respect the ratio of rotative travel of the side wall of the container from the glue pickup point 31 to the area 28 of the label pickup end of the pack must equal the horizontal distance or length of the container track or narrow runway strip 32 from the glue pickup point 31 to the area or point of the label pickup end of the pack. Rotative or other slippage between the side wall 33 of the container and the narrow track or runway strip 32, see FIGS. 9 and 30 of the drawings, will upset this ratio and cause the glue spotted portion 34 of the container sidewall to be out of registration with the predetermined area of the label pickup end where the glue spotted portion of the can contacts the pickup end area 35 of the top label or pack, see FIG. 55 of the drawings.

For purposes of reducing this possibility of misregistration to a minimum the conveyor or can feed belt spring loaded pressure rollers 22 of group 21 are provided with means for adjusting the pressure of their respective spring members 25, as shown particularly in FIG. 3 of the drawings. In this respect the bar brackets 23 have partially threaded openings 36 in which are slidably positioned shanks 37 having spring positioning heads 38 at their lower ends that engage and position the upper ends of springs 25 as shown. The upper ends of the shanks are engaged and adjustably positioned against the pressure of springs 25 by Allen type screws threadedly engaged in the threaded portions of openings 36, providing adjustable stops for the shanks and means to adjustably control the spring pressure of pulleys 22 against the conveyor belt within the zone of pulleys 22, this zone as shown covers slightly more than the maximum traverse of the containers from the glue pickup to the initial label pickup area.

In the initial feeding of soft side walled, aluminum or vacuum types of cans through the present machine and particularly as identified with the passage of the cans through the glue pickup area and related to the belt pressure elements of group 21 where the cans are fed

or rolled on their side walls over a narrow track by the pressure exerting single belt 12 that contacts the upper center or median side wall area 33' of the can when in feeding position and the bottom center or median side wall area 33'' of the can contacting its bottom support or narrow runway strip 32, the width of which is approximately the same as the conveyor belt 12 and substantially in alignment therewith, it is highly important to control the concentrated downwardly directed belt pressure, particularly as to the belt pressure rollers 22 in group 21, and the reacting upwardly directed pressure of the narrow supporting track 32 against the bottom side wall area 33'' of the can. In view of the belt and track being in superposed alignment and directing their diametrically opposed pressures against the upper and lower side wall areas of the can for such a comparatively small and narrow can area the conveying pressure for the cans in the area of group 21 becomes critical where a maximum belt feed pressure is highly desirable to convey the cans in a positive manner from the glue pickup to the initial label pickup point, but not so much so as to cause the side walls of the above referred to type of cans, that are highly sensitive to side wall pressure, to collapse, become out-of-round or dented.

Upon the initial and partial wrapping of the label about the can through the conveying action of the single belt and the rotative action of the can the label becomes interposed between the side wall of the can and the belt, allowing the belt to press the label tightly against the can preventing slippage of the label, should the glued end of the label not be holding properly when the rotative movement of the can pulls the label out from under the spring loaded curling bar after paste has been applied to the lap end of the label. This contact relation of the belt with the label produces a tighter wound label than would be a label applied by a labeling machine having the usual two conveyor belts that contacts only the closure beading at the opposite ends of the can.

Labeling machines depending on the two belt system for conveying cans through the machine have difficulty at times due to slippage between the belts and the respective opposite end beadings of the cans due to the small narrow area of belt contact and particularly when the cans are somewhat wet. In this instance the undrained water tends to puddle at the inside groove area of the beading, keeping the beading in a wet condition and depriving the belts of proper traction with the beading and thereby causing slippage and interfering with the timing and sequence of proper operation. With the use of the present single belt arrangement there is no slippage in this respect due to the belt contacting the smooth regular cylindrical surface of the can wall where water does not accumulate or puddle.

Referring to FIGS. 2, 4 and 5 of the drawings the drive motor assembly 8 comprises a motor 40 an expandable V belt drive pulley 41 mounted on the shaft thereof, the pulley being of the variable Reeves drive type that expands and contracts depending on the screw adjusted position of the movable base support for the motor as shown to vary the speed of its driven V belt 43 to control the speed of the machine as a whole.

For purposes of driving the conveyor belt run over pulley 13 the motor driven belt 43 drives the large V belt speed reduction pulley 44 fixed to rotating shaft 45 supported by the upright frame members 10, this shaft

also carries and has keyed thereto the small further speed reduction sprocket 46 which in turn drives the larger speed reduction sprocket member 47 by its sprocket chain 48. Sprocket 47 is fixedly supported on the intermediate driven shaft 49 carried by bearing brackets 50 mounted on the upper respective side frame members 1 and 2', this shaft also has fixed thereto and drives sprocket 51 which in turn drives upper elbow joint sprockets 52 and 52' by sprocket chain 53. With particular reference to FIG. 26 showing the details of the articulated segments or sprocket drive elbow joint assembly 54 it will be noted the sprocket members 52 and 52' are mounted, keyed and fixed to a common sleeve member 55 by the respective key 56 and Allen screws 57 as shown. The sleeve is provided with a bronze bearing bushing 58 for its total length. The sprockets are held in spaced relation on the sleeve by the Allen screws 57, and the sleeve 55 acts as a spacer for the ends 65 and 66 of the drive supporting arms and provides the clearance space 72 between the opposed faces of the arms to allow free movement between the opposed faces of the arms at the elbow area. The bushed sleeve and sprocket members are mounted as a unit to freely turn on the fixed supporting shaft 60. The respective opposite ends 61 and 62 of the shaft are in turn supported in the respective openings 63 and 64 of the elbow joint ends 65 and 66 of the respective drive supporting arms 67 and 68.

The end 62 of the shaft is held fast in the upper end arm opening 64 of the arm 68 by the Allen screw 69 and the opposite end 61 is provided with a collar 70 held in fixed position on the shaft end by set screw 71 and holds the two arm ends in snug rotative relation with the ends of the spacer sleeve 55.

Each of the arms or articulated supporting frames 67 and 68 are somewhat U shaped in transverse cross section and are each provided with respective cover plates 73 and 74 as shown and held fast to the respective arm members by screws 75 and 76 thus providing a housing, guard and support for the respective articulated drives.

The elbow joint sprocket 52' in turn drives through its respective sprocket chain 77 the sprocket 78 mounted on and keyed to the rotating shaft 79 supported in the vertically movable or elevating bearing bracket 80. The end 81 of the drive supporting arm 67 is also mounted on and movably supported on the shaft 79 as shown. The sprocket 78 through its shaft directly drives the belt run over pulley 13 also fixed to the shaft for driving the single conveyor belt 12.

The lower end 82 of the arm 68 is mounted and supported on the sprocket shaft 49 and has a partial rotative relation thereto. The arms 67 and 68 as to the respective opposite ends of each arm have free and independent movement in relation to their supporting shafts 49, 60 and 79 in their movement of adaptation to the various adjusted heights of the belt drive pulley 13. Shafts 49 and 79 are each respectively provided at their outside ends with fastening collars 83 and 84 to retain the arm ends on their respective shafts similar to and for the same purpose as collar 70 on shaft 60.

The articulated or elbow type drive for the power driven conveyor belt pulley 13 comprising its sprocket, chain drive and articulated arm members provides positive means for driving the pulley 13 without slippage, lost motion or backlash and self adaptable to various adjusted heights of the belt pulleys 13 and 14 suitable

to the different sized cans run through the machine. This drive is also self adaptable to the adjustment of the height of the belt pulleys during the operation of the machine when it is desirable to make a sensitive adjustment without stopping the machine and its labeling operation.

For purposes of simplification, reducing the machine parts and to provide greater accessibility from the front of the machine to the can conveying and labeling operations without the usual supporting obstructions on this side of the machine for the conveyor belt and its respective run over pulleys the present single belt, its respective driving and supporting pulleys 13 and 14 and their respective shafts 79 and 79' are supported from the rear side of the machine by their respective overhanging extensions or bearing brackets 85 and 86 these overhanging extensions therefor have supported ends and unsupported free ends and are identified with the respective delivery and feed ends of the machine as shown particularly in FIGS. 3 and 4 of the drawings. It will also be noted from these figures that the pulley assembly or bar brackets 19 and 20 for supporting the horizontal bar member 17 are each rigidly attached to the overhanging extensions or bearing brackets 85 and 86 by screws 19' and 20' for the respective bar supporting brackets.

The overhanging extensions or bearing brackets 85 and 86 each have integral depending head structures 87 and 88 respectively and fastened in and on one side of each head by set screws 89 and 90 respectively are round pulley assembly supporting bars 91 and 92 having rack teeth 93 and 94 respectively formed on one side of the lower part of each of the bars for a distance equivalent to substantially one half the length of each respective bar and may be identified as rack bars.

For purposes of elevating and lowering the can conveyor belt, its supporting and driving elements together with the spring loaded belt pressure rollers and their horizontal supporting bar 17 by means of the toothed vertical supporting rack bars or racks 91 and 92, the toothed portions of the respective rack bars are enmeshed with the respective pinion gears 95 and 96 keyed to the shafts 97 and 98; also carried and fixed to these respective shafts are worm gears 99 and 100 which in turn are engaged with and actuated by the respective worm members 101 and 102 keyed and fixed to and near the opposite ends of the elongated common shaft 103 that actuates both worm members. The said pinions, worms gears and the ends of the shaft member 103 are all respectively supported by and have bearing relation with the respective frame supported bearing brackets 104 and 105 as shown.

The opposite ends of the shaft 103 are each supported in the respective twin bearings 117 and 118 of the bearing brackets 104 and 105 and the respective worm members with their thrust bearings are each positioned between each of the respective twin bearings for purposes of giving the worms a solid bearing support. In this respect it may be noted the respective combined bar and rack members 91 and 92 are positioned in the respective guide bearings 106 and 107 of the bearing brackets 104 and 105 and have sliding relation therewith. The said guide bearings are located in the respective outwardly extending upper portions 108 and 109 of the bearing brackets 104 and 105 as shown. Also fixedly positioned in these upper extensions by respective set screws are supplemental stiffening and

strengthening bars 110 and 111 and are fixed stationary bars that are positioned in parallel relation to bars 91 and 92. The upper portions of these respective stiffening and strengthening bars are slidably positioned in the respective bushed guide bearings 114 and 115 in the depending head structures 87 and 88 and have snug fitting sliding engagement therewith.

The horizontal bar 17 for supporting the conveyor belt pressure rollers and their assemblies with its end brackets 19 and 20 rigidly fastened to the bar ends by screws 17' and to the respective overhanging extensions or bearing brackets 85 and 86 by screws 19' and 20' provide a rigid assembly to prevent pivotal turning of the respective conveyor belt pulley assemblies and their supporting bar and rack members 91 and 92. In this respect the respective supplemental strengthening bars 110 and 111 also contribute to preventing pivotal movement of the overhanging extensions or brackets and their supporting bars and racks 91 and 92. However the primary purpose of these supplemental strengthening bars to the supporting rack bars is to help in an indirect manner to carry the overhanging weight of the above referred to assemblies that otherwise would be wholly carried by the rack bars 91 and 92. In this respect the relatively long upper bearing engagement of the respective strengthening bars 110 and 111 with their respective upper bearings 114 and 115 provide positive supplemental means to prevent overhanging weight, sag or downward tilting of the above recited assemblies and thereby maintaining constant dependable belt pressure on the cans or packages.

Referring again to the elongated common shaft 103 identified with the means for raising and lowering the conveyor belt assemblies, the shaft has keyed and fixed thereon the bevel gear 116 positioned next to the inner bearing 117, this bevel gear in turn is enmeshed with and driven by bevel gear 116' keyed and fixed to its transverse supporting shaft 119 which in turn is supported by bearing brackets 120 and 121 carried by the respective rear and front upper frame members 1 and 2'.

Referring particularly to FIGS. 12, 45 and 46 of the drawings the transverse shaft 119 is held and prevented from moving longitudinally by the fixed position of the bevel gear 116' on one side of the bearing 120' and the fixed collar 122 on the other side thereof, see FIG. 12. For purposes of conveniently turning the shaft 119 with a conventional type of socket and pin crank the end 119' is provided with a slot 119" for engagement with the crank for adjusting the position of the overhang conveyor belt assemblies. After an adjustment in this respect is made it is important to fix or lock the shaft 119 for purposes of maintaining the said conveyor assemblies in adjusted position. To this end the shaft locking or clamping assembly 123 is provided comprising the disk member 124 fixedly held to the shaft by its integrally attached boss or collar portion 125 and its set screw. The outer face of the disk bears against the inner face of the shaft bearing 121' for stabilization. Substantially in line with this face is the arcual clamping surface or face 126 of the fixed arcual abutting and clamping surface of the extension 127 of the bearing bracket 121. Positioned above this extension is another bearing bracket extension or heel 128 that acts as a fulcrum point and is rectangular in shape as to its face having a step or shoulder 129 formed on its face for positioning the upper end of the clamping lever plate 130 that

has fulcrum engagement therewith and to prevent the lever plate member from turning. The opposite end 131 of this plate overlaps and has clamping engagement with the inner face 124' of the disk when in clamped position. The plate is held in operative clamped position by the tightening screw member 132 that is threadedly engaged to the clamping lever plate 130 as shown, which in turn is supported in the bracket screw hole 133. Upon tightening the screw member the end 131 of the lever and clamping plate clamps the disk between the plate end 131 and the arcual face 126 of the bracket extension 127. When it is desired to turn the shaft 119 for an adjustment it is only necessary to back the screw off a couple of threads to free the disk from its clamped position for purposes of turning the shaft 119 for an adjustment.

Referring to FIGS. 1, 2, 9 and 12 I have shown can guide bars 140 and 141 positioned slightly above the top bed of the machine and running substantially the full length thereof and positioned towards the rear or far side and front or near sides of the machine respectively. Guide bar 140 is a plain type of solid bar but guide bar 141 comprises and supports a flexible and comparatively thin ribbon like resiliently mounted can guiding and engaging strip 142 running substantially parallel with the bar 141 for the greater portion of its length and stops slightly short of the extreme opposite ends thereof. This strip provides a yielding frictional and continuous guiding surface for the cans when being conveyed between the guides 140 and 141 to keep the cans from cocking whereby the longitudinal axes of the cans are maintained in a transverse position to the guides and to their direction of travel over the supporting bed and runway of the machine. The flexible strip 142 is yieldingly actuated by helical springs and supported by the guide bar member 141 by pins 143 fixedly attached at their inner ends to the strip member and slidably supported in the bar pin holes 144. The outside ends 145 of the pins with their washers are held in place by cotter pins 146. The helical compression springs 147 are mounted on the pins as shown and their opposite ends bear under pressure against the inner face of the strip 142 and the inner shoulders 148 of the enlarged or socket portion of the pin holes for purposes of providing resilient support for the flexible can guide strip member 142. In view of the strip being comparatively thin and flexible and being yieldingly supported the strip readily adapts itself to frictional pressure engagement with the contacting end of the can and is equalized between the two guides and in an independent manner from the preceding and following cans that are also being frictionally engaged under spring pressure by the thin flexible strip. In this respect the cans are independent of each other as to the pressure of the cans on the strip when the cans are moving through the machine in spaced relation and in a substantially continuous manner the strip tends to slightly undulate.

This undulation of the thin flexible strip 142 is caused by the articles or cans 149 exerting pressure on the strip and causing the strip to be slightly depressed and thereby forming independent flexed areas in the strip, and in the immediate vicinity of the ends of the cans 149 and in view of the spaced relation and movement of the cans the comparatively thin strip is caused to undulate. These flexed areas being less in length than the

distance between the cans thereby providing an unflexed portion between the cans.

The extreme opposite ends 150 and 151 of the strip at the respective feed and delivery ends of the machine, see FIGS. 10 and 13, are pulled back towards their supporting guide bar 141 as shown to provide the necessary clearance for the cans for free entry into and deliverance from the machine.

For purposes of providing means for adjusting and controlling the spacing between the guide bars 140 and 141 to suit various sizes of cans, the respective guide bars each have attached thereto by screws at 155 and 155', and 156 and 156' near their respective opposite ends as shown outwardly extending arm brackets 157 and 157', and 158 and 158', which in turn are pivotally engaged as shown to the respective actuated bell cranks 159 and 159', and 160 and 160', by the respective shouldered screws 161 and 161', and 162 and 162'.

The respective inwardly directed arms 163, 163' and 164, 164' of the bell cranks each have fixedly engaged thereto at their ends by set screws as shown upwardly extending respective pin members 165, 165' and 166, 166'. The upper ends of the pins 165 and 165' being pivotally connected by tie rod 167 and the upper ends of pins 166 and 166' being also similarly connected in a pivotal manner by tie rod 168. Both tie rods are adjustably mounted for purposes of properly aligning the can guide bars 140 and 141 whereby the bars will be in parallelism in relation to each other. In this respect each tie rod is provided at its opposite ends with eye bolt type of connectors 169 that have pivotal bearing engagement with the respective upwardly extending pin members 165, 165', 166 and 166'. Upper and lower collars 170 and 171 are fixedly positioned on the pins by set screws above and below the connectors for holding the same in position as shown. The opposite ends of the tie rods are threaded for the threaded engagement with the threaded bolt portion of the eye bolt connectors 169 as indicated at 172 particularly as shown in FIGS. 3 and 4. Lock nuts 173 are provided on the threaded portion of the connectors to maintain the threaded engagement between the tie rods and their respective connectors in locked position. Each of the guide bars 140 and 141 are slightly flared outwardly at their opposite feed and delivery ends for purposes of substantially matching the slightly wider feed and delivery runways carrying cans to and from the machine.

The pivotal centers of the respective bell cranks at the delivery end of the machine are mounted on shouldered scrws 174 and 174' and supported on upper extensions 120' and 121' of bearing brackets 120 and 121 respectively, and the respective pivotal centers of the bell cranks at the feed end of the machine are fixedly mounted by pins as shown at the top of the respective upright bell crank activating shafts 175 and 175'. These shafts in turn are supported in upper and lower bearing brackets 176 and 176' on the rear side and in bearing brackets 177 and 177' on the front side of the machine, both shafts are held in proper longitudinal relation to their respective bearings by the fixed collar members 178. The said upper bearings 176 and 177 are each respectively supported on the upper frame members 1 and 2 of the machine as shown and the said lower bearings 176' and 177' are each supported on the upright frame members 9 as shown.

For purposes of rotating the bell crank actuating shafts 175 and 175' to increase or decrease the spacing between the can guide bars each of these shafts are respectively provided near their lower ends with respective left and right handed worm gears 179 and 180 fixedly engaged to their respective shafts which in turn are in meshed engagement with their respective left and right handed worm members 181 and 182 carried and fixedly positioned on the adjusting shaft 183 which in turn is supported at its opposite ends by bearing brackets 184 and 184' fastened to the upright frame members 9 as shown. The outside projecting end 185 of the shaft is provided with a wrench engaging slot 186, see FIG. 27, for engagement therewith by a conventional type of pin and socket wrench when it is desirable to turn the shaft for adjusting the spacing of the can guide bars 140 and 141.

Referring particularly to FIGS. 10 and 27 disclosing locking means for the adjusting and actuating mechanism for the can guide bars wherein the bell crank 160 differs from the other three bell cranks in that it has an arcual shaped extension 187 and an arcual shaped slot 188 in the extension with the axis of the arc of the arcual slot being the same as the axis or center of the bell crank 160 to allow free arcual movement of the slot with a tightening and locking screw. Positioned in this slot is the tightening or locking screw 189 with a washer member spanning the slot opening. The screw 189 is threadedly engaged at 190 to the upwardly disposed extension 191 of the bearing bracket 177. Thus for purposes of readjusting the position of the can guide bars 140 and 141 the locking screw 189 is loosened sufficiently to give free movement between the slot and locking screw, an appropriate wrench attached to the slotted end 185 of the adjusting and actuating shaft 183 and the shaft suitably rotated for the necessary adjustment of the can guides. Upon completion of the adjustment the locking screw 189 is retightened to the changed position of the arcual slot of the bell crank extension 187.

The heavy adhesive or glue pot 30 located at the feed end 27 of the machine is provided with a pair of underlying supporting round rack bars 200 on which the glue pot rides to various positions of desired adjustment. The opposite ends 201 and 202 of these bars are adjustably supported respectively by the cross frame bracket 203 and the elongated plate bracket 204. The ends 201 of these rack bars 200 are fixedly supported on the frame bracket 203 by screws 205 which in turn also support the discs 206 positioned between the ends 201 of the rack bars 200 and the adjustable frame bracket 203 supported on the upright frame members 9 by screws 207 positioned in the screw slots 208 of the frame members 9. These slots provide means for adjustably raising or lowering the rack bar ends 201 by the frame bracket 203 and thereby adjusting the position of the glue pot 30. With particular reference to FIGS. 6, 16 and 36, the opposite ends 202 of the rack bars 200 are fixedly attached to and supported by the adjustable plate bracket 204 by screws 209 which also support disc members 210 interposed between the bar ends and the plate bracket 204 as shown. The adjustable plate bracket 204 is attached to the large plate member 211 by screws 212 positioned in slots 213 in plate bracket 204 for purposes of providing means for allowing the raising or lowering of the bracket 204 and

bar ends 202 and glue pot 30 to a desired adjusted position.

The large plate member 211 is provided with slightly elongated openings 216 for the heads of each of the screws 209 with sufficient clearance about the heads to allow for normal adjusting movement of the plate bracket 204. In view of the rack bars being positioned directly under the glue pot, also providing supporting means therefor and on which the glue pot rides by means of its bearing supporting brackets it is important to prevent glue splashings or spillage from the pot reaching the rack bars. For this purpose each of the rack bars are provided with superposed semicircular dirt and splash guards 214 covering the upper half of each bar throughout their lengths. The opposite ends of each guard conform to and are respectively supported by and attached to the disc members 206 and 210 at the opposite ends of the rack bars 200 by screws 215 as shown.

The glue pot is provided with two pairs of bearing brackets 217 and 218 positioned on the underside and at the respective outer longitudinal bottom edges of the pot and fastened thereto by screws 219. The arcual or half round bearing portions 220 and 221 of the respective bearing brackets 217 and 218 have direct glue pot load bearing engagement with the rack bars as shown. Each of the bearing brackets have openings 222 into which the upper arcual portions 220 and 221 of the bearings project upwardly with sufficient clearance in the limited opening space above the arcual bearing portions to allow for the passage therethrough of the arcual or semicircular guard members in view of the conformation of the shapes of the guards and bearing portions 220 and 221, thus allowing guard protection of both the bearings and rack bars at all times.

For purposes of readily moving the glue pot 30 and its attendant elements to an adjusted position along the rack bars 200, each of the rack bars are provided with toothed racks 223 on their underside areas throughout their length. Each rack has enmeshed therewith pinions 224 fixedly mounted on the transverse adjusting pinion shaft 225 rotatively supported in bearings 226 which form an integral part of the rack bar bearing brackets 218. The pinion shaft 225 is prevented from having longitudinal displacement due to the outer faces of the pinion collar type extensions 227 being in abutment with the inner faces 228 of the bearings 226. The front outer end 229 of the pinion shaft 225 is provided with a wrench engaging slot 230 for attachment thereto by a conventional type of pin and socket wrench for turning the shaft for purposes of moving the glue pot assembly to a desired adjusted position.

It should be fully understood where reference has been made to moving the glue pot to an adjusted position, this moving of the glue pot is primarily identified with the glue spotting mechanism as a whole and identified specifically with the proper relative high or upper substantially center area of the glue applying wheels at the desired point of applying or spotting glue to the side cylindrical wall of the can, as this point is the critical and primary consideration in moving the glue pot to an adjusted position.

With this in mind and with particular reference to FIG. 30, the glue spotting wheels 29 are formed into separate groups 231 and 231' positioned respectively on each side of the narrow can track 32 and may be of any desired number. The two inner wheels 232 of the

respective groups are so positioned that one of each of the two wheels are in juxtaposition to the narrow can track 32 on each side thereof and fixedly mounted on the power driven glue pot shaft 233 and held fast thereto by set screws 234 engaging an appropriate longitudinal flat 235 on the shaft at a desired adjusted position. Positioned next to each of the outer faces 232' of each of the glue spotting wheels 232 and in spaced relation therewith are subgroups of spotting wheels 236 and 236', the wheels of which are fixedly held together and in spaced relation as to each group by the respective spacing collars 237 and 237'. The glue spotting wheels 29 and their respective spacing collars of each subgroup are carried by and held in their fixed relative positions on the respective sleeve like hollow screw members 238 and 238', each of said members comprising a head at one end, and a threaded portion and nut member at the opposite end. The binding effect of the tightly turned nut of each subgroup holds the spotting wheels and spacers in fixed relation on each of the respective sleeve like hollow screw members 238 and 238'. The said subgroups and screw members are each carried on the common shaft 233 and held in fixed adjusted relation thereto by set screws 239 engaging the respective longitudinal flats 240 for each subgroup. Each of the set screws 239 pass through holes in the sleeve portions of the respective screw members 238 and 238' as shown to reach their respective engaging flats 240. The inner glue spotting wheels 232 and the subgroup assemblies may be moved along their supporting shaft to various adjusted positions through their respective set screw adjusting members.

Further adjustment as to the spacing between the spotting wheels of the subgroups may be made by reducing or enlarging the widths of the collar like spacers 237 and 237', all for the purpose of adjusting the positions of the glue spotting wheels to meet the requirements of cans of different lengths. The purpose of the subgroup wheel assemblies is to save time and work effort in that only two adjustments are necessary for the two subgroups of multiple spotting wheels in the present instance for the average variations in can lengths whereas otherwise it could be six or more depending on the number of separately adjustable glue spotting wheels used.

The glue spotting wheels and the drive shaft 233 therefor are driven by the gear 241 fixedly mounted on the outer end of the shaft 233 which has a bearing 242 in the end wall of the glue pot and its opposite end supported in the bearing bracket 243 mounted within the confines of the glue pot and with a shaft end collar 244 fixed to the shaft to prevent longitudinal movement of the shaft. The glue pot is provided with the usual drain outlet 245 and stop valve 246. It is also provided with an electric heating element 247 and the electric wiring 248 therefore from a source of current supply. The temperature of the glue in the pot is thermostatically controlled, the details of which are not shown. The heating element 247 is positioned within the elongated inverted U shaped recessed bottom structure 249 of the glue pot and held fast against the bottom of the pot by Allen type set screws 250 that impinge against the bottom of the heater structure to hold the same in place against the bottom surface of the pot. The inverted legs of the U are formed by the two depending side flanges 251 having side extensions for the bearing bracket screws 219. A bottom plate 252 is provided to protect

and cover the bottom area of the heater. This plate has an enlarged depending front portion 253 forming a housing for the wiring terminals of the heater together with a screw held cover plate 254 to close the front opening of the housing and to shield and protect the terminals 255. The plate member 252 is held fast to the bottom ribs or flanges 251 by screws 256.

As will be noted from the above description and particularly the drawings the glue pot proper is carried wholly on the rack bars 200 positioned away from and below the underside of the glue pot with an air gap therebetween and having very limited contact therewith by the comparatively narrow bearings brackets 217 and 218. In the present instance it takes approximately one-half the time to preheat the glue preparatory to the initial operation of the machine and substantially one-half the amount of electric current to maintain glue at a normal operating temperature for a given set of conditions as compared to those found and set up in a similar machine with similar conditions of set up but where the glue pot is mounted in such a manner as to be identified somewhat directly with the side frame of the machine through which the heat of the glue pot is dissipated and absorbed.

Referring to the means for driving the glue spotting wheels 29 the gear 241 fixedly mounted at the far end of the shaft 233 is driven by gear 257 fixedly mounted on driven shaft 258 supported by the bearing bracket 259 attached to the rear end of the glue pot by screws as shown. Also carried at the far end of shaft 258 is a driven bevel gear 260 fixedly engaged to the shaft by the cotter pin 261, bevel gear 260 in turn is driven by the bevel pinion 262, that is slidably engaged to its longitudinal drive shaft 263, and keyed thereto, the shaft having a keyway 264 running along the shaft for the greater distance of the length of the shaft. The sliding bevel pinion gear 262, as shown particularly in FIGS. 3 and 10, is provided with an L shaped type of key 265 for engagement with the keyway 264, the upturned end 266 of the key prevents the key from leaving the pinion in view of its position in the radial recess 267 in the end face of the pinion with a key retaining washer 268 positioned against the end face of the pinion and the recess to hold the L-shaped key in place. The washer in turn bears against the outwardly extending pinion retaining face plate 269 supported on the side bearing bracket 259 by screws 270. In view of the angular enmeshed relation of the pinion with the bevel gear 260 and its fixed bearing relation through the washer against the face plate the keyed pinion is held in fixed longitudinal relation between the bevel gear and the pinion retaining face plate and is free to move along the shaft 263 but is maintained in driven relation with the shaft at all times irrespective of its longitudinal position on the shaft. Thus upon any forward or rearward adjustable movement of the glue pot the above drive assembly moves with the glue pot in constant drive engagement for the glue spotting wheels 29 and therefor the relation to and between the assembly and the longitudinal keywayed driving shaft 263 is always of a positive driving nature. The glue pot end of the shaft 263 is supported in the bearing 176' of the bearing bracket 176 and the opposite end in the bearing bracket 271. An additional bearing bracket 272 positioned approximately midway of the length of the shaft provides an additional support for the shaft. Each of these bearing brackets are sup-

ported by and attached to the rear side frame 1 by screws as shown.

With reference to FIGS. 4, 7 and 12, the end of the shaft 263 supported by bearing bracket 271 has fixedly attached thereto the bevel gear 273 enmeshed with and driven by bevel gear 274 fixedly mounted on the transverse shaft 275 which also has a bearing support in the bearing 276 of the bearing bracket 271 with its opposite end supported in the bearing bracket 277 screw attached to the upper frame bar 2' with a collar 278 positioned next to the inside surface of the bearing to prevent longitudinal movement of the shaft. This shaft in turn is driven by reduction gear sprocket 279 fixedly mounted thereon which in turn is driven by sprocket chain 280 and pinion sprocket 281 fixedly mounted on the intermediate drive shaft 49 the driving of which has been hereinbefore described. Thus providing a constant drive from the motor 40 for the glue spotting wheels 29 at their various adjusted glue spotting positions.

It will be noted from FIGS. 32 and 33 the bottom plate 252 of the glue pot is held tight against the bottom ribs 251 of the glue pot by screws 256 and this, together with the front closure plate 254, prevents spillage or splashing of glue from reaching the heater member 247.

With reference to FIGS. 1, 10 and 11 it will be seen the upper near or front longitudinal frame bar structure of the machine is made up of two separate frame bars 30 2 and 2', the inner ends 2" and 2''' of the respective two bars are separated and spaced from each other for a distance slightly greater than the maximum adjustable travel of the glue pot. This spacing permits the front end of the glue pot to project outwardly, through and 35 beyond the plane of the front side surfaces of the respective frame bars allowing this end of the pot to be somewhat in the open and away from the upper frame structure of the machine as shown, for purposes of making it more convenient to introduce a supply of 40 glue to the pot and to replenish the same when needed. This space or open area also allows for increasing the capacity of the pot by increasing its length and to make it more convenient to clean the same.

45 A paste pot 282 positioned near the center rear portion of the machine provides a reservoir of paste through which a paste pickup belt 283 passes for purposes of introducing the paste from the belt to the trailing or lap end of each top label of a pack just before the labels are removed from the label pack. The paste 50 being applied just prior to the operation of the pulling of the label from the pack and from under a label curling and paste spreading bar; the broad operating principle of which is fully shown and described in the hereinbefore referred to Wild Pat. No. 1,627,946.

55 For purposes of controlling the amount of paste left on the belt after passing through the paste of the paste pot and before the belt enters the operating area of the machine, a novel type of paste belt scraper 284 is provided for purposes of removing surplus paste from the belt and leaving a predetermined amount of paste on one side of the belt to be fed into the label pasting mechanism of the machine.

In the present instance the paste belt scraper bracket 60 284 comprises a head portion 285 with an arm like extension 286 terminating in a bearing head portion 287 pivotally mounted on the pin member 288, the opposite end of which is fixedly positioned in the pin holding

head portion 289 of an arched supporting bracket 290 therefore, the opposite end 291 of which is fixedly attached to the movable frame bar bracket 293 by the screw 292, this bracket also supports the paste pot assembly. The pivotal mounting of the scraper bracket causes the scraper head 285 to contact and rest on the paste belt by a pressure only equal to the pivotal weight of the scraper head and its supporting bracket. This arrangement prevents undue wear, injury or tearing of the belt and gives a longer operating life to the paste belt than would otherwise be had where operating pressure is dependent upon springs and adjusting screws.

The pin holding head portion 289 has still another extension 290' formed integral therewith that has fixedly attached to the underside thereof a plate 294 over which the paste belt 283 runs and for supporting the free end of the scraper bracket 284 that engages the upper surface 296 and side walls of the top flight of the paste belt. The outer end of the plate is provided with an integral tongue like extension 297, the width of which is substantially the same as that of the paste belt, the outer end 298 of which is slightly curved downward where the paste belt initially contacts the tongue extension of the belt supporting plate for purposes of removing paste from the bottom of the belt and to prevent undue wear to the bottom or inside surface thereof.

The belt pulley 299 and path of travel of the belt from the pulley are in alignment with the tongue extension 297 of the plate member and the inverted U shaped slot portion 300 of the scraper head 285. With reference to FIGS. 21, 22 and 23 the legs of the inverted U-shaped slot of the scraper head being formed by the downwardly extending leg portions 301, that function as a belt guide and to scrape paste from the sides of the belt, and the base of the U being formed by the belt scraper portion 302 at the top of the slot for scraping excess paste from the top of the belt.

The belt scraper portion 302 comprises two flat paste removing and belt contacting faces 303, between which are positioned paste passage slots 304 and 304' having a paste quantity controlling valve 305 located between the inner ends of the respective slots for purposes of permitting only a predetermined amount of paste to be passed from the leading slot 304 to the discharge slot 304' and to remain on the longitudinal center area of the paste carrying surface of the paste belt before entering the pasting mechanism of the machine. The swinging or pivoted weight of the scraper head bearing against the top surface of the belt being sufficient to overcome the viscosity of the usual density of paste used for this purpose and is sufficient to prevent lifting of the scraper head by the pressure of the paste to crowd past the scraper head and its control valve.

The primary paste scraping or leading edges 303' of the two paste removing flat faces 303 function to initially remove excess paste carried on the moving paste belt from each of the top longitudinal side surfaces 306 of the belt, but leaving an accumulated amount of paste in the leading slot 304. A portion of which is then carried under the bottom face 307 of the valve 305 where the thickness or height of the paste may be reduced, as shown, depending on the setting of the valve face 307 as to its distance from the top face of the moving paste belt. Although the paste tends to spread when entering the somewhat circular valve chamber 308 immediately under the valve face 307 after it leaves the leading slot

304 it is again reduced in width as it passes from under the valve into the discharge slot 304' which is of the same width and height as slot 304. As may be noted the effective adjusting height of the valve is dependent on the heights of the slots.

The valve 305 as a whole is in the form of a valve stem like structure having a slightly enlarged threaded body portion 309 threadedly engaged to the threaded opening 310 in the scraper head, for purposes of conveniently adjusting the height of the valve by turning the knurled valve head 311. The lower stem portion 312 has a somewhat snug but rotatable sliding fit in the stem guide hole 313 for purposes of reducing to a minimum any accumulation of paste between the stem 312 and the wall of the stem guide hole 313. Any unforeseen accumulation in this respect would tend in the course of time to dry and freeze the stem in its guide hole preventing adjustment of the valve. To prevent and counteract this freezing effect a small amount of a conventional type of lubricating or commensurate liquid is introduced between the walls of the stem and its guide hole. For this purpose the knurled valve head 311 is provided with a conventional type of ball and spring self closing oil valve 314 having a press fit for its casing in the head opening 315, the opening in turn being connected with an oil gland 316 positioned and running through the center of the valve structure but coming to a blind end 318 at a point located approximately midway of the length of the valve stem 312 and having an oil or the like discharge opening 317 at the blind end leading to the outside of the valve stem to introduce oil or a commensurate liquid between the walls of the stem and stem guide hole 313 to prevent the drying of paste between the walls and the resultant freezing effect to the valve assembly.

With reference to FIG. 29 of the drawings, after the moving paste belt leaves the scraper with its ribbon of paste 319 it passes through the machine to the opposite or front side thereof where it passes through a belt tensioning assembly 320 slidably and adjustably supported on the upper front frame bar 2' by its U shaped frame straddling and engaging bracket 321 that engages the frame on three sides, the remaining side being engaged by an abridging plate 322 fastened to the upper and lower legs of the U bracket by screws 323 for purposes of retaining the bracket to the frame 2' as shown. Mounted on the front of the bracket in holes 324 and held therein by set screws 325 are two superimposed spring supporting bars 326 extending outwardly away from the front face of the bracket sufficiently to slidably support a belt tensioning head 327. Positioned on each bar between the face of the frame bracket and inner structure of the belt tensioning head are compression springs 328 for purposes of applying free resilient tension and pull to the endless paste belt throughout its length. It is the intent that the amount of this resilient tension in the present instance is predetermined by the reaction of the springs for normal operation of the machine over a long period of time for purposes of getting away from the human element of constantly releasing and reapplying hand tension to the belt between prolonged periods of inoperation, such as at the end of a days operation and the beginning of a new days operation. It has been found the tendency of the machine operators is to pull the belt too tight and then fix the position of the belt tension by a set screw or the like. This tends not only to shorten the life of the belt by tearing

or breakage but also when too much tension is applied to the belt it prevents the efficient application of paste to the label from the belt.

The belt tensioning head 327 is slidably supported on the bars 326 by a pair of elongated press fit bushings 329 supported in the lower half of the head member as shown. The purpose of mounting the belt tensioning head 327 by dual bearing supports with a pair of tension equalizing compression springs mounted on the supports is to prevent the head from swinging downward and to maintain an upright position and also the dual bearing supports and twin springs prevent binding and cocking of the tensioning head due to the constant pull of the endless paste belt on the head member and the compression springs 328 whereby the head will have a free resilient tensioning support adaptable to slight variables in the length of the belt due to stretching under normal operating conditions.

The upper portion of the tension head 327 is provided with paste belt idler pulleys 330 and 331, rotatively supported on the respective shafts 332 and 333 which in turn are supported in the respective openings 334 and 335 in the head structure and fixedly engaged thereto by set screws as shown.

The moving paste laden belt engages and passes under a portion of the lower part of pulley 330 and thence moves up, over and around a greater portion of pulley 331 somewhat forming a loop and thence moves through the label pasting portion of the machine, then over the paste pot idler pulley 336 supported within the paste pot 282 on the far side of the machine, thence looping around the power driven paste belt pulley 299 supported within the paste pot and thence moving to the hereinbefore described paste belt scraper 284. It being understood the length of the endless paste belt is such that when the belt is in full normal operating position it is sufficiently short as to compress the tension springs thereby maintaining the belt under constant operating tension.

In view of the ribbon of paste, after it leaves the scraper, being positioned on the top or outer face of the upper flight of the endless belt and passes under idler pulley 330 in the same position it is necessary to undercut the center of this pulley as shown at 337 (see FIG. 11) for a depth and width sufficient to clear this strip of paste to prevent the same from coming into contact with the belt engaging surfaces of the pulley. Upon the paste belt leaving pulley 331 the paste carrying side of the belt is facing downwardly and in operative position for applying paste to the label when depressed.

When it is desired to relieve the belt of prolonged inoperative tension and to disengage the belt from the tension head pulleys, such as at the end of a day's operation, it is only necessary to apply sufficient inward pressure against the tension head so as to additionally compress the spring members whereby the belt may be removed and freed from the tension pulleys on the open side 338 of the head structure and conversely when the belt is to be again mounted on the pulleys of the tension head assembly sufficient inward pressure is applied to the head and spring assembly to move the head inward far enough to allow the paste belt to be remounted on the pulleys of the tension head and then released to reapply tension to the belt.

As may be noted in FIGS. 6 and 7, the tension as applied to the moving paste belt is sufficient to keep the paste laden belt suspended above the top label of the

label pack as shown. The belt is only momentarily pressed downward sufficiently to cause the paste of the belt to be transferred to the top label by the passage of a can traveling on the can track 339 coming into contact with the raised belt depressors 340 in the path of the can causing the same to be depressed and thereby depressing the paste belt by the respective heels 341 of the depressors. Upon the passing of the can the tension of the belt raises both of the belt depressors to their normal raised position preparatory to repeating the operation by the passage of the next can. The inverted L shaped wire depressors are each freely pivoted to the label guide brackets 342 by pins 343 and lightly rest upon the bottom flight of the belt by their respective heel members.

Attached to the adjustable cross bar 344 by screws 345 is an elongated L shaped angle or label stack abutting member 346 having a label stack engaging foot 347 that engages the end edge of the stack to hold the labels down in snug formation at the paste applying area of the stack to prevent the labels from fluffing up and to maintain a uniform space between paste belt and the top end face of the label stack. In view of the clearance between the top label and the paste laden paste belt being quite narrow any fluffing up of the labels at this point may cause the labels to contact the paste belt prior to the actuation of the belt depressors, causing an undesirable accumulation of paste at the label end area of the stack. In view of one end of the adjustable cross bar 344 being fastened to the adjustable paste pot and paste belt supporting bracket 293 by screw 348 on the far side of the machine and its opposite end being fastened to the adjustable supporting bracket 321 for the belt tension head assembly by screw 349 the relative position between the paste belt and the label stack abutting member 346 that is supported by the bar are substantially constant at all times.

Referring to FIGS. 11, 13 and 14, the large paste belt pulley 299 located within the paste pot 282 is power driven and by means of which the paste is picked up by the belt from the paste pot and initially removed therefrom in controlled amounts by the belt scraper member with the residue from the scraper falling back into the paste pot. This belt pulley is fixed to and carried on driven shaft 350, supported in the elongated separate bearing member 351 having an integral flange type head 352 fastened to the outside wall of the paste pot by screws 353. The head, covering and sealing the opening 351' through which the bearing passes. The inner end of the shaft is provided with a fixed collar 354 having positioning abutment with the pulley member and the opposite or outside end having the male half 355 of a clutch assembly fixedly engaged thereto by key 356 and set screw 357. This portion of the clutch comprises a collar like head member 358 having a pair of press fit pins 359 diametrically positioned therein and projecting outwardly therefrom sufficiently for engagement with a matching pair of holes 360 in the female half 361 of the clutch assembly. This half of the clutch assembly is in the form of a combination clutch and sprocket wheel 362 freely mounted on a pin type of shaft 363, having a head 364 at its inner end for retaining the sprocket wheel and its opposite end fixedly positioned by set screw 365 in the inner and outer extending bosses 366 of the clutch and drive supporting housing 367. The sprocket wheel 362 is driven by sprocket chain 368 and driving sprocket wheel 369

keyed to and in sliding engagement with the power driven shaft 263.

The drive support and housing 367 is attached by screws 370 to an extension 371 of the movable frame bracket 293 to which the paste pot 282 is demountably attached by screws 372, which when removed allows the paste pot to be shifted slightly to one side sufficiently to disengage the clutch pins 359 from their holes 360 when the paste pot may be fully removed from the machine for cleaning. It being understood the paste belt as having been fully disengaged from the pulleys and belt scraper of the paste pot prior to this pot removal operation. In this respect it may be noted the removal and freeing of the belt from the scraper may be accomplished by the simple operation of raising the scraper head sufficiently to allow the belt to be freed from the inverted U shaped slot portion 300 of the scraper head, or if need be, the scraper assembly may be readily and easily removed entirely for special attention by pulling it off its supporting pin 288.

The label pack guide brackets 342 are each slidably supported on their respective longitudinal bracket supporting bars 342', see FIG. 28, the upper portion of each bracket having positioned therein a pin member 380 that projects slightly above each bracket sufficiently to position and mount thereon roller members 381. These rollers and pins are each respectively positioned in the two elongated slots 382 formed on the underside of the adjustable cross bar 344, whereby upon forward or backward longitudinal movement of the bar the label pack guide brackets 342 normally positioned on each side of a label pack will be caused to be moved along their respective supporting bars 342' accordingly and to a position suitable for a label pack of a given length.

For purposes of providing a single and common means for simultaneously adjusting and positioning, according to the length of a given label pack for normal operational function therewith, the assemblies of the paste pot and drive therefor, the paste belt and its tensioning means, the spring actuated label curling and paste spreading bar 373 with its supporting levers 374 that are fixedly engaged to and positioned near the respective opposite ends of the transverse bar 375, these ends are respectively supported in the movable paste pot supporting bracket 293 and the movable supporting bracket 321 for the self tensioning assembly for the paste belt, the label pack guide means and label pack lap end hold down means, the machine is provided with the movable frame brackets 293 and 321 positioned on the far and near side of the machine respectively, each having attached thereto by screws 376 elongated toothed rack bars 377, each positioned and movable in guide brackets 378 therefor fixedly attached to their respective frame bars 1 and 2' by screws 379. Each of the rack bars have intermeshed therewith rack actuating pinions 383 fixedly positioned on and near the opposite ends of the transverse pinion supporting bar 384, the ends of the bar being supported in the bracket bearings 385, with the near end of the bar having fixedly attached thereto a knurled knob member 386 for turning the rack actuating pinions for moving and positioning the said assemblies.

The said assemblies are all interengaged and interconnected as shown and described whereby they may be moved longitudinally by the rack and pinion adjusting means in a simultaneous manner as a single assem-

bled unit whereby each said assembly is moved to its proper longitudinal position in unison with the other said assemblies for normal operational function in relation to a label pack comprised of labels of a given length that come within the minimum and maximum length that the machine is adapted to handle.

The discharge ends 391 of the supporting bars 342' for the label pack guides 342 and 387 are supported on the threaded follower brackets 388 carried on the multiple threaded screw bar 389 supported by the brackets 378 and positioned on the brackets 388 by pins 390. These ends 391 also support the ends 392 of the can tracks through the fixedly held block members 393. The feed ends 394 of the supporting bars 342' for the label pack guides are supported on the threaded follower brackets 395 carried on the multiple threaded screw bar 396 supported by upper frame brackets 397 and positioned on the follower brackets by pins 398. The label pack guides 387 positioned on and near the feed ends 394 of the bars 342' provide supports for the slightly elevated can tracks 339 which are respectively fastened at their feed ends 399 to the pack guides by screws 400 and thereby provide means for fixing the position of the said guides.

25 The transverse spacing between the respective slightly elevated can tracks 339 may be readily varied to suit different sized cans by turning the respective multiple threaded bars 389 and 396 causing the respective threaded follower brackets 388 and 395 of each pair to move inwardly or outwardly in respect to the longitudinal center of the machine in view of each of the threaded bars comprising both right and left handed threads similar to the structure in this respect as disclosed in the prior Art patents referred to herein and the means for turning and adjusting these bars and their respective follower brackets to various positions is also similar thereto.

Referring to this transverse movement of the label pack guides 342 that respectively carry the combined pin and roller members 381 that are engaged with and movable in their respective slots 382 of the transverse bar 344, provide means for constant engagement of these label pack guides with the transverse bar irrespective of the transverse adjusted position of the guides, whereby upon longitudinal movement of the bar to an adjusted position the guides will be moved accordingly.

Referring to FIGS. 19 and 20 showing means for turning the threaded bars the multiple threaded screw bar 389 which is divided into right and left hand threaded portions has an elongated opening 401 throughout its length in which is slidably positioned the shaft 402 having a sprocket 403 fixedly positioned at the rear end thereof enmeshed with an endless sprocket chain 404 the opposite end of which is enmeshed with the sprocket 405 fixedly carried on the rear end of the multiple threaded screw bar 396 whereby upon simultaneously turning the threaded bar end 389 and its inner shaft 402 as a unit for positioning the lateral label pack guides the threaded screw bar 396 with its lateral label pack guides will also be moved in a similar manner through the interengagement of the respective sprockets by the chain member. For purposes of conveniently turning the respective screw bars either singly or in unison in a simultaneous manner the shaft 402 has fixedly engaged to its front end a balanced hand crank 406 together with a pin 407 passing through the shaft

402, near the base of the crank, with a drive fit, having its opposite ends extending outwardly and away from the shaft member sufficiently to engage diametrically positioned collar slots 408 formed in a collar member 409 fixedly carried at the end of the reduced sleeve portion 410 of the hollow screw bar 389 by the tapered pin 411 and set screw as shown. The sleeve portion 410 is supported in the opening 412 of the knobbed adjusting sleeve like threaded member 413 provided for adjusting the longitudinal position of the screw bar member. A spiral compression spring 414 is positioned about the rear end of the shaft 402 between the inner face of the sprocket 403 and the far or rear end sleeve portion 415 of the screw bar 389. The constant thrust of the spring against the face of the sprocket tends to pull and hold the pin 407 in engaged position with the slots 408. Thus when in this position and the hand crank is turned both the shaft 402 and the hollow screw bar 389 will be turned in unison as well as the screw bar 396 through the respective sprockets and chain members, and causing all of the lateral label pack guides to be moved simultaneously. When it is desired to move only the label pack guides identified with the screw bar 396 for a particular compensating adjustment it is only necessary to withdraw the pin 407 for disengagement from the slots 408 by pulling back on the hand crank compressing the spring 414 during the turning operation, causing only the shaft 402 with its attached sprocket 403 to turn and thereby through the attendant chain 404 and sprocket 405 to cause only the screw bar 396 to be turned. Upon releasing the hand crank the pin 407 will snap back into engagement with the slots 408 through the action of spring 414.

When the screw bar 396 is turned slightly, for alignment purposes, independently of the other stationery screw bar, causing its respective followers 395, the label pack guides 387 and the feed ends 394 of the guide supporting bars 342' to move towards or away from the longitudinal center of the machine there is a tendency of the bars 342' to have a slight pivotal action on the pins 390 and 398. The bars being sufficiently free on these pins for this purpose. It will be noted the multiple threaded screw bar 396 also has a similar knobbed threaded member 413' to the knobbed member 413, for longitudinal adjustment of the screw bar 396 as a whole.

Each of the respective pairs of threaded follower brackets 388 and 395 carried by the multiple threaded screw bars have attached thereto respective pairs of hanger members 416 and 417 positioned respectively in the end slots 416' and 417' for expanding or contracting through the movements of the screw followers the self adjusting primary label feed table 418, supported and fed upward by the primary label feed mechanism 4. This specific self-adjustment of the table by the hangers is shown in the patent to Henthorn referred to herein.

Referring to FIG. 6 of the drawing, each of the lateral label pack guides 342 and 387 on the far or near side of the machine have attached thereto the depending movable hanger 342' and the fixed hanger 387' which act as guides for the near side wall of the label pack while the feed end hanger members 417 also provide guide means for the feed end of the label pack as shown in FIG. 54 of the drawings.

For purposes of providing means whereby the top of the label pack at the label pick up area will be main-

tained in a horizontal position irrespective of variables in label thickness particularly towards one end thereof causing the pack to be thicker at one end, the label feed table 418 is pivotally supported by the bracket 419 and pivot pin 420 and yieldingly held in a substantially horizontal position by the compression spring 421 and spring pressure regulating nut and stud assembly 422 threaded supported on the bracket extension 423 with interengaging stop members 423' to limit the upward movement of the table member for purposes of allowing the table to yield downwardly at one end due to these variables in label and pack thickness brought about primarily by variables in printing ink thickness, embossing and the like. The table and supporting bracket therefor is pivotally attached to a rack and feed bar 424 by screws 425 and 426. The purpose of the pivotal attachment is to prevent undue binding between the label table engaging hanger members 416 and 417 and the respective table slots 416' and 417'. A cushion spiral spring 427 freely positioned about the feed bar and interposed between the underside of the bracket 419 and the lower frame plate 428 through which the bar passes through free opening 429. The spring absorbs impact shock when the table is lowered too fast or inadvertently dropped and rests at all times on the frame plate. A hand cranked raising and lowering mechanism for the label table together with an automatic feeding of the table and label pack by the rack feed bar 424 actuated by the primary feed mechanism 4 will be hereinafter described.

The secondary label pack supporting assembly 7 comprises a pair of outwardly disposed arms 430 having attached and free end and each carrying a plurality of label pack supporting members 431 comprising label pack engaging fingers 432 with means for automatically retracting the fingers after they have served their label pack supporting purposes. These arms and label pack supporting members are fully disclosed in the Henthorn patent referred to herein, otherwise the assembly 7 distinguishes over the Henthorn structure. Each of the arms 430, at their attached ends are each respectively engaged to the top portions of the pivoted and downwardly disposed yielding arm like extensions 433 by screws 434. Each of these extensions are pivotally supported between the ear like projections on the pivot shafts 435 which in turn are carried by the projections 436 that are an integral part of the adjustable twin bearing brackets 437. The lower ends of each of the yielding arm like extensions 433 are provided with spring adjusting screws 446 with their threaded ends positioned in spring engaging socket and flange members 447, the opposite ends 448 of the compression springs 449 are positioned in hollows 450 formed in lower extensions 451 of the twin bearing brackets 437. This spring assembly provides the arms 430 with the necessary yielding support for the label pack. In view of the constant pressure against the arm 433 by spring 449 each of the brackets 437 are provided at their upper portions with upwardly extending stops 446 against which the upper portions of the arm like extensions 433 and the attached ends of the label pack supporting arms 430 impinge to prevent the arms moving above the horizontal. The twin bearings 437' of each integrally formed bracket being slidably mounted on the superposed transverse shafts 438, the purpose of which is to primarily provide strength to and prevent twisting of the brackets 437 due to the projected load

of the label pack on the extended label pack supporting and feeding arms.

The superposed transverse shafts 438 each have free ends and are both fixedly positioned by set screws midway of their length in shaft holes 439 in the supporting head bracket 440 therefor that is fixedly mounted by a set screw in the bracket hole 441 on the top portion 442 of the secondary rack and supporting feed bar 424'. A cushion spiral spring 444 is freely positioned about the secondary feed bar and normally rests on the frame plate 428 and through which the bar passes by way of the free opening 445 of the plate. The function and purpose of this spring is similar to that of cushion spring 427.

For purposes of transversely adjusting the yielding arms 430 and their label pack supporting members 431 to increase or decrease the spacing between these elements for adaptation to different width label packs, each of the threaded follower brackets 395 have fixedly engaged thereto by screws 452 downwardly depending guide bars 453 having abutting and sliding engagement at their lower ends with a transverse adjustable positioning bar 454 to maintain the guide bars 453 in proper vertical alignment with the rack and feed bar 443 and the twin bearing brackets 437. The positioning bar 454 has adjustable engagement throughout its length with its supporting transverse angle bar 455 by the respective screws and slots 456 and 457 distributed throughout the length of the angle bar 455 which in turn is fixedly supported and positioned at its opposite ends on the lower frames 3 by screws 458. The vertical leg of the angle bar in turn is fastened to the lower portion of the plate 211 by screws 459 distributed along its length and provides a positioning support for the plate, the opposite outside ends of the bottom outside edge of the plate are supported on the respective front and rear lower frames 3.

Each of the twin bearing brackets 437 are provided at their back portions with elongated U shaped channels 460 that interengage and straddle and also have vertical sliding engagement with guide bars 453 that act as ways in the present instance and as shown particularly in FIGS. 6 and 9, for purposes of causing any transverse movement of the guide bars to be transferred to the brackets 437. These channels 460 are similar to the U-shaped channels positioned at the back of the upper follower brackets 395 in which the upper portions of the guide bars 453 are fixed as shown in plan in FIG. 16. Thus upon movement of the follower brackets 395 and their attached hanger members 417, which also function as guides for one end of the label pack and provide means for adjusting the width of the primary label pack supporting table suitable for labels of a particular width. The depending guide bars 453 that are also attached to the follower brackets 395 are also similarly moved transversely at the same time and thus causing the twin bearing brackets 437 and their attendant secondary label pack supporting elements 7 to be moved simultaneously therewith to an adjusted position for a particular width label like that of the setting of the primary label pack supporting table.

In FIGS. 6 and 9 the primary label pack feed table 418 is shown at the bottom of its stroke which is the usual position for introducing a fresh pack of labels to the primary feed table and the secondary label pack supporting assembly 7 is shown in a position that would be substantially normal for the upward feeding of the

labels or label pack when wholly supported and being fed by the secondary assembly 7.

The primary and secondary label pack supports and their respective power driven automatic feeding mechanisms 4 and 5 for the label packs may be operated separately or together and in unison. These respective primary and secondary elements may also be freely raised or lowered by their independent and separate combination clutch and hand cranks when disengaged from their respective automatic feeding mechanisms.

In the normal initial operation the machine is set in motion and several packs or a stack of labels is placed on the primary label feed table 418 when positioned at the bottom of its stroke, and the hand crank 470 of the primary feed is in a pulled out position sufficiently to disengage the automatic primary feed mechanism therefrom, to be hereinafter described, and then turned clockwise raising the table 418 until the top labels of the stack are in normal upper operative position, similar to that shown in FIG. 55, whereby the labels may be readily picked up off the top of the stack by the passing glue spotted cans in the usual manner, the hand crank 470 with its clutch mechanism 471 is pushed inwardly until the clutch is fully engaged with the primary automatic feed mechanism. With this clutch engagement the automatic feeding of the labels immediately takes place.

Referring to FIGS. 38 and 40 it will be noted the primary rack and feed bar 424 has attached at its lower end an extending arm 472 the outer end of which adjustably supports an upwardly extending bar 473 positioned in the opening 474 by the set screw 475. The upper end of the bar has adjustably mounted thereon a transversely directed bell clapper activating arm 476 having an opening 477 in which the bar is adjustably positioned by the set screw 478. The bell clapper 479 is yieldingly or flexibly supported in an extended horizontal position by a closely wound spring like member 480, whereby as the arm 476 moves upward due to the action of the primary automatic feed it contacts the tip portion of the clapper member flexing it upwards until it slides off the arm 476 and reacts sufficiently to strike the bell 481, giving the operator an audible signal that the supply of labels remaining in the machine and being fed by the primary table was running low and needed to be replenished before the remaining supply was exhausted.

During this period of operation of the primary feed the secondary feeding mechanism is idle with its hand crank 482 and its associated clutch assembly 483 both in disengaged position with the secondary automatic feed mechanism. However, the hand crank 482 when in this position may be used to raise or lower the secondary label pack supporting assembly 7 in a similar manner to that for raising and lowering the primary table by its hand crank 470. The detailed means for the hand crank raising and lowering of the table 418 and the secondary assembly 7 will be hereinafter described.

Upon hearing the bell signal the operator turns the secondary hand crank 482 clockwise raising the secondary label pack supporting assembly 7 from its low position, as shown in FIG. 1, to an upper position of snug engagement with the underside of the label pack being supported and automatically fed at the time by the primary feed table 418. In this operation, the secondary label pack supporting fingers 432 of the members 431 pass through their respective registering table slots 484

positioned along each side of the expandable table bar members as shown in the Henthorn patent and engage the underside of the label pack. The secondary hand crank 482 and its clutch 483 is pushed inward to form engagement with the secondary automatic label feed which in turn begins to also feed the remaining depleted stack of labels upwards without interruption to the normal operation of the machine. The primary automatic feed is then disengaged by pulling the hand crank 470 out sufficiently to disengage the clutch and lowering the table to its normal bottom position by the hand crank, a fresh stack of labels positioned on the table, the loaded table raised by the hand crank until the top of the stack snugly contacts the under side of the upper supply of labels and the under side of the secondary label pack supporting fingers 432. The primary hand crank is then moved inward engaging the primary clutch and automatic label feed, enabling the primary feed to again take over the label feed operation without interfering with the continuous operation of the machine. Upon this primary feed take-over the secondary feed is stopped by pulling the hand crank 482 out, disengaging its clutch and then lowering the secondary label pack support 7 to its normal bottom position of rest by its hand crank 482 to await its next cycle of operation. Upon lowering the label pack support 7 the secondary label pack supporting fingers 432 are automatically withdrawn from between the labels of the upper and lower packs as fully shown and described in the referred to Henthorn patent.

With particular reference to FIG. 40 of the drawings the respective hand cranks, clutches and gear drives identified with each of the primary and secondary label feeds are similar in structure and operation in that each of the respective hand cranks 470 and 482 are provided with integral hub structures 485 and 486 mounted on shafts 487 and 488, having their outer faces recessed at 489 and 490 in which the respective hand crank stop collars 491 and 492 fixedly mounted on shafts 487 and 488 rest when the hand cranks are in withdrawn position for the disengagement of their respective clutch assemblies 483 and 483' and when it is desired to raise or lower the respective primary or secondary label pack feeding supports.

Each of the respective hubs have fixedly positioned in equally distanced diametrically opposite holes therein by set screws a pair of clutch pins 493 and 494 having constant but sliding engagement in the respective pairs of holes 495 and 496 in the collars 497 and 498 fixedly positioned on the respective shafts 487 and 488 by their respective keys and set screws as shown. The shafts each have a respective pair of supporting bearings 499 and 500 in the depending primary and secondary brackets 501 and 502 respectively. Fixedly positioned within the said respective brackets by keys and set screws on the respective shafts are gears 503 and 504 having engagement with and for actuating the respective primary and secondary toothed rack and feed bars 424 and 424'.

Freely mounted on each of the respective shafts 487 and 488 are clutch gear members 505 and 506 positioned between the respective fixed clutch collars 497 and 498 and the depending brackets 501 and 502 to maintain their lateral position. These brackets are rigidly secured to the under side of the lower frame plate 428 by screws as shown. Each of the clutch gear members 505 and 506 are provided with four pairs of dia-

metrically opposed holes 507 and 508 respectively equally distributed and spaced in a circular manner and from their respective longitudinal axes over their respective outer faces 509 and 510. The spacing between centers of the holes of each pair being substantially the same as the spacing between centers of the pins 493 and 494 as well as the holes 495 and 496 of the fixed collars 483 and 483' for purposes of permitting ready registration and engagement of the pins with the respective clutch gears from various relative rotative positions of the hand cranks 470 and 482 to the respective clutch gears when the hand cranks are moved inward for clutch engagement with their respective automatic feed. In this FIG. 40 the hand crank 470 of the primary feed is shown in full withdrawn position whereby the label pack table 418 may be raised or lowered directly by the hand crank and the hand crank 482 of the secondary feed is shown in full "pushed in" position wherein the secondary clutch is in a fully engaged position and the clutch pins 494 in complete engagement with the clutch gear 506 whereby the secondary label pack supporting assembly 7 may be fed upwardly for the automatic feeding of the labels. It may be noted each of the hand cranks is always connected to its respective shaft and toothed rack actuating gear through each of their respective fixed collars 483 and 483' and each of the clutch gears are also connected in a like manner through the fixed collar members when their respective clutches are in engaged positions.

30 The automatic label feeding mechanisms for both the primary and secondary means for feeding the labels is driven from a common source of power. This source is the power driven transverse shaft 275 having a V belt pulley 511 fixedly attached thereto, driving a V belt 512 which in turn drives a V belt pulley 513 fixedly attached to a short shaft 514 supported in the bearing bracket 515 attached to the lower frame 3 at the far side of the machine. Also fixedly attached to shaft 514 and driven thereby is another V belt pulley 516 driving V belt 517 which engages and drives V belt pulley 518 fixedly attached to and driving cam shaft 519 having bearing supports in frame bracket 520 and the bearings 521 of the primary feed bracket 501. Fixedly attached by key and set screw to and driven by the cam shaft 519 is a primary and secondary feed actuating cam 522 that actuates a cam follower member 523 in a predetermined intermittent manner that is determined by the position of the follower in relation to the cam surface of the cam. The follower having means to render the same effective or ineffective in relation to the cam for the feeding or non-feeding of the primary or secondary label pack feeding means, the details of which will be hereinafter described.

55 This follower is rotatively attached by a screw pin 524 to a pivotally rocking plate or label feed bellcrank 525 having clamping means for tightly clamping the split opening 526 of the plate about the outer race structure of an over-running clutch member 527 comprising a clamping screw 528. This clutch 527 is similar in design to that shown in FIGS. 39 and 44 for clutch 527' and the inner race 529 of the clutch is fixedly positioned on the bellcrank pivotal and supporting shaft 530 by the pin 531. Positioned concentrically in the annular space between the outer and inner races are a plurality of sprags similar to those indicated at 532 and shown fragmentarily in FIGS. 39 and 44. These sprags act as wedges and when in the angular position as

shown convey positive clockwise motion imparted to the outer race to the inner race and thence, in the present instance, to the shaft 530 due to the inner race being fixed to the shaft by pin 531. Conversely when the outer race is driven counterclockwise the sprags do not grip the clutch surface of the inner race and the clutch is ineffective. This particular type of clutch and the other three overrunning clutches identified with the present label feed mechanism are all similar in structure each having outer and inner races with gripping sprags positioned between the races and represent a commercial product known as "A Formsprag Clutch" manufactured by Formsprag Clutches Co., 23601 Hoover Road, Warren, Mich. It is understood the present feed mechanism is not limited to the use of this specific over-running clutch.

The supporting shaft 530 for the bellcrank 525 and its overrunning clutch 527 is supported in bracket bearings 523 and has fixedly attached at its opposite end by key and set screw a drive pinion gear 534 that is in constant mesh with the primary clutch gear 505. Upon rotative feed motion being applied to the shaft, as indicated by the arrow, the drive pinion turns the clutch gear 505, and if the primary clutch assembly 483 is in engaged position, like that shown in FIG. 40 for the secondary feed clutch 483', the primary feed shaft 487 will be turned, turning primary toothed rack engaging gear 503 and causing the primary feed rack 424 to be fed upwards for the automatic feeding of the labels.

During this period of the intermittent upward feeding movement of the rack the total weight of the rack and its attendant label pack supporting table with its stack of labels is carried by the enmeshed teeth of the gear 503 engaging the teeth of the rack 424. Upon the limited rotative feeding stroke of the reciprocal movement of the overrunning clutch 527, the gripping action of its sprags that are similar to the sprags 532 shown in FIG. 39 and at a similar angle, carry this weight and prevent the shaft from reversing its feeding movement. However upon the outer race of the overrunning clutch 527 making the return stroke of its reciprocal movement there is no gripping resistance on the shaft by its sprags and they would tend to move back with the outer race allowing the shaft 530 to drift back until the outer race reached the end of its return stroke. To prevent this backward drifting and the reversal of the shaft 530 an auxiliary and similar overrunning clutch 527' is provided and supported on the outer end of shaft 530 as shown in FIG. 39 with its inner race 529' fixed to the shaft by pin 531' and its outer race 535 held in clamped position by the clamping screw 528' in the split opening 526' of the fixed positioned arm 536. As shown the upper portion of this arm with its auxiliary overrunning clutch 527' is supported on shaft 530 and the lower extended end 537 is screwed tightly and in fixed relation to one end of a flat stationary connecting bar 538 by the screw 539. With this arrangement it is understood this arm is maintained in a fixed position. Thus with the outer race 535 of the auxiliary clutch 527' being held in a fixed position the sprags 532 at all times engage the inner race in a positive gripping manner in a counterclockwise direction and prevents the shaft 530 from rotating or drifting in a reverse or nonfeeding direction in view of the inner race 529' being pinned to the shaft 530. With this locking effect of the auxiliary overrunning clutch 527' against counterclockwise movement of the shaft 530 the primary rack and label feed bar 424

cannot be normally lowered unless the primary clutch 483 is disengaged by pulling the hand crank 470 out to disengage the clutch. This frees the clutch gear 505 from positive engagement with its supporting shaft 487 and allows this shaft to be freely turned in either direction by the hand crank to either lower or raise the label feed rack by the hand crank independent of the automatic feed as this disengagement of the primary clutch neutralizes the effectiveness of the automatic upward feeding of the feed bar or rack 424.

In FIG. 40 the clutch assembly 483' identified with the secondary automatic upward feeding of the rack or label feeding bar 424' is shown in fully engaged position allowing the secondary automatic upward feed to be fully effective and is somewhat similar in its action in this respect as shown and described for the primary feed and its respective primary clutch mechanism.

The bell crank 525 and its cam engaging follower 523 not only activates the primary label feed but also the secondary label feed mechanism. In this respect the narrowed bottom extension 540 of the bell crank is pivotally connected by a ball and socket assembly 541 to a threaded head 542 of an adjustable connecting bar 543. The opposite end of the bar also has a threaded head 544 pivotally connected to the bottom portion 545 of the secondary overrunning clutch feeding arm 546 by a ball and socket assembly 547. The two threaded heads are interconnected and threadedly engaged by the respective right and left hand threaded ends of the connecting rod 548, with lock nuts 549 at each of the interthreaded ends to fixedly position the respective interthreaded members after their relative positions have been determined by the setting of the adjustable connecting bar 543. Thus any forward feeding motion of the bell crank 525 with its respective over-running clutch 527, is carried to the secondary feeding arm 546 and its respective over running clutch 558 by the connecting rod 548.

For purposes of yieldingly holding the follower 523 under spring tension and in engagement with its cam member 522 during the feeding periods of the primary or secondary feeding mechanisms and to provide a positive forward feeding action with a spring return for the feeding elements, a return tension spring 550 is provided, one end of which is attached to the pin 551 carried by the fixed bar 538 with its opposite end attached to the pin 552 carried by the collar 553 which is adjustably mounted on the connecting rod 548 to determine the tension of spring 550 and held in fixed position thereon by a set screw as shown. The opposite end, from that previously described, of the fixed flat bar 538 is also held in a fixed tightly screwed position to the lower narrow end 554 of the secondary over-running clutch supporting arm 555 by the screw 556 as shown in FIG. 40. This arrangement causes the bar 538 to be maintained in a fixed position.

The feeding operation of the over-running clutches identified with the secondary label feeding mechanism is similar to that of the over-running clutches identified with the primary feed mechanism. In this respect the rocking or reciprocating movement of the bell-crank 525, caused by the cam and follower members activates the secondary over-running clutch supporting arm 546 through the connecting rod 548. This arm is provided with a split opening 557, similar to that shown in FIG. 39, in which is positioned the secondary feed over-running clutch 558 like that shown in FIGS. 39

and 44 having sprags like those indicated at 532, with inner and outer races, and held in clamped position therein by the clamping screw 559 and positioned on the shaft 560 with its inner race 561 fixedly held to the shaft by pin 562.

Thus on the feeding movement of the secondary over-running clutch 558, its sprags grip the shaft 560 causing the shaft to be partially rotated together with the pinion gear 563 fixedly carried on and at the opposite end of shaft 560 supported in bearings 564 of the depending secondary bracket 502. This feeding movement of pinion gear 563 is transmitted to the larger secondary clutch gear 506, with which it is constantly engaged, this clutch gear is freely mounted on clutch shaft 488, the turning of which is not effective to feed the secondary label pack supporting assembly 7 unless the secondary clutch 483' is in engaged position, with the clutch pins 494 engaging the holes 508 of the gear 506, as hereinbefore described. When in this engaged position, shaft 488 and its feed bar engaging gear 504 is partially rotated for each feeding operation, feeding the toothed rack and feed bar 524' upward. The partial rotative feeding motion of both the primary and secondary over-running clutches 527 and 558 respectively is very slight or a few degrees and this amount of movement is further reduced to about one-half by the reduction gearing 534 and 505 for the primary feed and reduction gearing 563 and 506 for the secondary feed. This intermittent feeding operation in the present instance becomes activated and is sensitive and responsive for the thickness of units of about eight labels of normal thickness as they are removed from the top of the label pack by the over running cans in the pickup operation, to be hereinafter described.

The secondary shaft 560 on which is mounted the over-running feed clutch 558 also carries an auxiliary over-running clutch 564, the structure and function of which is similar to the auxiliary over-running clutch 527' carried on the primary shaft 530 to prevent backward drifting of shaft 560. During the secondary feeding operation when the control clutch 483' is in engaged position and the over-running feed clutch 558 partially rotates shaft 560 on its feed stroke, it also turns reduction gears 563 and 506 together with gear 504 that engages and lifts the secondary rack bar 424'. The attendant weight of this rack bar and its superstructure tends to cause the rack bar to descend turning gears 504, 506 and 563 in a reverse direction from that of the feeding direction when the sprags of the over-running feed clutch 558 no longer grip the inner race of the clutch fixed to the shaft 560 by pin 562 when the outer race 565 and its activating arm 546 are on their return stroke by the action of the return spring 550. The auxiliary over-running clutch 564 is provided to prevent this reverse or backward drifting of the secondary feed shaft 560. This clutch, like that shown in FIG. 39, comprises an inner race 566 fixed to shaft 560 by pin 567, an outer race 568, with sprags like those indicated by reference numeral 532 in FIG. 39 disposed concentrically between the races. The outer race is held in a fixed clamped position in the split opening 569 in the fixed or stationary arm 555 by clamping screw 570. In view of the fixed position of both the arm 555 and the outer race 568 with the gripping angle or setting of the sprags being the same as those of the over-running feed clutch 558, the sprags will grip and hold the inner race 566 and shaft 560 against any coun-

ter-clockwise rotative thrust or movement, but allows free clockwise movement of the said inner race and shaft members. This feature of the invention may be readily seen by viewing FIG. 39 of the primary auxiliary clutch 527' that is used for the same purpose for the primary feed. Therefor irrespective of the release of the sprags for the return stroke from their feeding and gripping position as identified with both the primary and secondary over-running feed clutches there will be no backward drifting or reversing of their respective shafts due to the fixed gripping position of the sprags of the respective primary and secondary auxiliary overrunning clutches.

The period for the upward feeding of the labels by the secondary label pack supporting assembly 7 is of short duration as this secondary feeding period represents the necessary time from the take-over of the label pack by the secondary supporting assembly 7, to disengage the primary clutch 483, by withdrawing the clutch hand crank 470, turning the crank counter-clockwise to lower the primary label table 418 to its bottom position, reloading the table with fresh label packs, raising the loaded table by turning the handcrank 470 clockwise until the uppermost labels snugly engage the underside of the label pack being fed and supported by the secondary assembly 7, moving the primary handcrank 470 inward for full feeding engagement of primary clutch 483, thence withdrawing the secondary hand crank 482, which disengages the secondary clutch 483', causing the secondary feeding operation to stop, turning the hand crank 482 counter-clockwise lowering the secondary assembly 7 to its lowest or bottom position as shown in FIG. 1. It may be noted from the above that at the time of the changeover from primary to secondary feeding of the labels that these two feeds are operating simultaneously. In view of both feeds being operated from a single and the same source, i.e., the cam 522 and follower 523, the amount of the feeding impulse for each one is the same and neither one interferes with the other, thereby providing a smooth continuous feed during the changeover without interfering or upsetting the feeding rhythm.

During this changeover period of about 20 seconds or from the time the secondary label pack supporting assembly 7 begins to move upward in its feeding operation to the time the primary feed assembly takes over with a fresh supply of labels and the secondary feed assembly has been stopped in its upward feeding travel it will have traveled about one to one and a half inches or fed about 300 labels, for normal operation.

The label supporting assembly 7 does not move clear up to the can runway or label pickup area of the machine like the primary label table 418 but may stop somewhere near the position shown in FIGS. 6 and 9. It will be noted there is quite a reserve of labels left on the label support assembly 7 after it has reached its approximate stopping point as shown in fine dotted lines in FIG. 9. This point may vary somewhat depending on the operator as to the moment when he pulls the hand crank 482 out to disengage secondary clutch 483'. It will be noted in FIG. 6 the attached ends of the label supporting arms 430 and the upwardly extending stops 446' of the secondary label supporting assembly 7 are in line with and immediately below the screw follower brackets 395 and that these parts would contact, causing the machine to jam if the operator did not disengage secondary clutch 483' in time. To overcome this

possibility, and to stop the secondary feed operation short of the contact point between these members and for preventing the secondary over-running feed clutch 558 from continuing its feeding operation beyond a predetermined point, the secondary rack and feed bar 424' is provided with an adjustably mounted feedstop member 571 located near its lower end, comprising a base plate 572 having a split opening 573 in which the feed bar is positioned and clamped by the screw 574 at a fixed adjusted position. The far end of this plate has attached thereto an upwardly directed cam like feed stopping plate 575 having a slightly offset upper head portion with a substantially 45° angular cam top surface 576 that is directly beneath and in alignment with the reduced rounded lower end portion 545 of the secondary over-running clutch feeding arm 546 as seen particularly in FIGS. 38, 40 and 43. As the feed stop member is carried upward by the feeding action of the rack 424' its cam surface 576 contacts the lower rounded end 545 of the arm 546 causing the arm to be shifted to the left, as shown in FIGS. 38 and 40, and at the same time, through the connecting bar 543, also causing the bell crank 525 that carries the cam engaging follower 523 to also be swung to the left. This combined movement raises the follower sufficiently to clear the same of the operative effectiveness of the two high feeding points of the cam 522 and thereby rendering both the follower and cam inoperative as to the feeding action of both the primary and secondary over-running feeding clutches 527 and 558 respectively. The fact that the primary over-running feed clutch 527 is also rendered inoperative by the lifting of the cam follower 523 by the action of the secondary feed stop 571 this action is coincidental to the more important operation of stopping the upward feeding movement of the secondary label supporting assembly 7, as the primary power feed clutch 483 is normally in disengaged position, however should the primary feed clutch 483 be inadvertently engaged at this time this action would prevent the inadvertent operation of the primary feed. In this respect the primary feed has separate and distinct means to stop the primary label pack supporting assembly 6 when it has reached its predetermined maximum height substantially in a plane with the can runway and when the labels on the primary support are exhausted if additional labels have not been added to the primary supply and the primary table without its supply of labels has been fed upward to its maximum height.

It should be understood the operation of the feeding means for both the primary and secondary feeding of the labels is based on the principle that the power or actuating means for feeding the labels and their supports upward in an intermittent manner is normally held in a nonfeeding position and must be triggered or released automatically by the passage of cans on the runway when the machine calls for more labels. Each time the machine responds in this respect the upward feeding distance of one feed stroke or movement of either the primary or secondary label supports is equal to approximately six or eight labels. That this upward intermittent feeding operation of the primary and secondary feed will cease to operate and stop at any given upward feed point when there is no immediate requirement for additional labels at the label pickup point by cans being conveyed through the machine, as will be hereinafter described. There is an exception to the above explanation and that is the feed stopping action

of the secondary feed stop member 571 mounted near the lower end of the secondary feed rack bar 424' for stopping the primary and secondary feeding action of the machine, irrespective of the call of the machine for 5 more labels, principally for the purpose of preventing impact between the undersides of screw follower brackets 395 and the supported ends with their stops 446' of the yielding secondary label supporting arms 430, as previously described.

10 Referring to FIGS. 6, 9, 11, 16, 17, 38, 54 and 55, and particularly the last five mentioned figures, the machine is provided with a trip and latch mechanism for automatically starting, stopping and controlling the primary and secondary label feed mechanisms, comprising 15 a pair of latch releasing trip members 580 positioned on each side of the can runway and normally held in raised non-feeding position as shown by spring action, the trip members are pivotally positioned in the recesses 581 of the label pack guides 387 on opposite sides of the runway by screws 582. It will be noted from FIGS. 16 and 17 the cans are so guided and conveyed on the can runway as to cause the beadings of the cans to be in vertical alignment with and directly over the respective trips 580 whereby the beadings of the 20 cans when passing over the respective trip members 580, at the initial label pickup point, as shown in FIGS. 55, may or may not contact the trips, depending on the height of the labels over and above the respective top surfaces 583 of the trip members. Also noted in FIG. 25 55, the side walls of the cans contact the top of the label pack in the glue pickup operation of the labels by the cans. As the labels are removed the height of the top of the pack is lowered. This lowered height must be sufficient to not only allow the can beadings to contact 30 the top surfaces 583 of the trip members but low enough to cause the can beadings to push the trips down for a distance sufficient to raise the latch member 584 far enough to release the keeper 585 of the oscillating bell crank member 525, see FIG. 54 of the drawings. Both the latch and keeper are removably attached 35 to their supports for renewable purposes and are made of tough hardened steel for long wearing qualities. The latch 584 is attached to its supporting lever arm 586 by screws 587 and the keeper 585 is attached to the bell crank 525 by screws 588. As may be noted from FIG. 40 42, the keeper 585 projects outwardly from the plane of the supporting surface therefor of the bell crank for clearance purposes. The latch lever arm 586 is fixedly carried on the end of the pivotal shaft 589, supported 45 in bearings 590, formed integral with and positioned on each side of the depending primary bracket 501 with fixed collars to maintain the position of the shaft. This primary bracket 501 as well as the secondary bracket 502 are each rigidly fastened to the underside of the 50 lower frame plate 428 by screws 591 and 592 respectively. An additional or complementary lever arm 586' 55 to lever arm 586 is also fixedly attached to the pivotal shaft 589, and positioned substantially midway between the shaft bearing 590 or approximately in line 60 with the longitudinal center of the machine with its free end 593 disposed in the opposite direction from that of lever arm 586. This free end 593 is flat and of sufficient width to readily support by contact the bottom end, as shown, of an elongated adjustable head 594 threadably engaged to an upwardly extending rod 595 with a lock nut 594' to fix the position of the head, and pivotally engaged at its upper end 596 to the transverse cross bar 65

597 by way of a collar like connector 596' welded to the top end of the rod 595 with particular reference to FIGS. 6 and 9 the connector 596' is maintained substantially midway of the length of the bar 597 by collars 598 positioned on each side of the connector and fixedly engaged to the bar. The opposite ends of the bar are fixedly positioned in the free end openings 599 of each of the extending arm members 600. The opposite ends of the arms are each supported on the transverse bar 602 by their respective openings 601 and fixedly engaged thereto by set screws. Bar 602 runs parallel with bar 579, with its extreme opposite ends 603 being rotatively mounted and supported in the opposite end bearing brackets 604, which in turn are fastened near the upper corners of the large vertical transverse plate member 211 by screws 605.

The reduced free ends 606 of the latch trip members 580 rest on the top of the transverse bar 597 and project underneath the transverse frame plate 607, the underside of which together with the bar 597 protects and limits the movement of the free ends 606 of the latch trip members 580.

With reference to FIG. 16, it may be noted each of the inside edges of the feed ends 399 of the can tracks 339 are cut back at 608, in line with the recesses 581 and trip members 580, allowing for the trip members to be exposed to contact by the beadings of the cans in their passage through the machine should the height of the label stack be sufficiently low for the final triggering or tripping of the trip members 580 to start one of the intermittent feeding cycles of the label feeding mechanism, whereby the height of the labels is raised sufficiently to cause the beadings of the overrunning cans in the label pickup operation to clear the top surface 583 of the trip members and allowing them to be raised by spring action to their original nonfeeding locked position. This action of the cans is given an assist by the downward pressure upon the cans by the spring pressured conveyor belt 12. Further, this downward movement of the trip members is quite gradual to the point of actual release of the upward feeding action of the feed mechanism and is broken down to one label at a time.

The label feed triggering action identified with the above is the same for both the primary and secondary feeds and is as follows: Upon the gradual consumption of labels with the resultant gradual downward movement of the trip members due to the action of the passing cans a corresponding movement is transferred to the transverse bar 597 by the reduced ends 606 of the trip members being in contact with the bar, which in turn moves the verticle rod 595 downward, through its collar connector 596', causing its lower head member 594 that passes through guide openings 594' of the plate 428 and secondary bracket 502, to move the lever arm 586' downward and its associated lever arm 586 upward, through the pivotal action of cross shaft 589, raising and releasing the spring actuated latch 584 from its keeper 585 against the pull of the latch and lever spring 609, the opposite ends of which are attached by pins 610 and 611 to the lever arm 586 and the bellcrank 525 respectively. Immediately upon the release of the latch the follower 523 is freed to move down under spring tension to engagement with the constantly rotating cam 522, by the action of spring 550, that actuates connecting bar 543 and head 542 connected to the lower reduced extension 540 of the bell-

crank 525 causing the bellcrank to pivot about shaft 530 with its attached follower 523. Upon the initial upward feeding movement of the follower caused by one of the two high points 612 of the cam the bellcrank 525 and its primary overrunning feed clutch 527 are caused to rotate for a short distance about the axis of the primary shaft 530. This movement of the overrunning feed clutch 527 causes the shaft 530 to also move and if the primary feed control clutch assembly 483 is in engaged position the primary label feed mechanism is activated, as hereinbefore described, causing the labels to be fed upward for a single feed cycle, which is normal for regular machine operation. This feeding operation raises the height of the labels allowing the trips 580 to move up to their normal raised position and thereby prevents the beadings of the cans at the moment from depressing the trip members 580. The lifting of the trips to normal raised position is caused by the latch 584 snapping down in front of and engaging the keeper 585 due to the action of tension spring 609, substantially at the end of the feeding movement of the bellcrank 525 when enough clearance is allowed by the keeper to permit the latch 584 to snap down into locked position with the keeper 858. This position is shown somewhat diagrammatically in FIG. 54. FIG. 38 shows the cam, follower, latch and keeper in their normal positions after the latch has been raised by the depressed trip members and the feed return spring 550 has moved the bellcrank and keeper 585 under the latch with the follower 523 contacting one of the low sides of the cam just prior to the feed movement of the bellcrank and its overrunning feed clutch.

The above referred to elements and explanation relating to the primary feed also applies to and activates the secondary feed. In normal operation of the secondary feed the secondary feed control clutch assembly 483' is fully engaged and that of the primary feed is disengaged. In view of the feed and nonfeed return movements as well as idling or inactive periods of the bellcrank 525 are all transferred from the bellcrank through the connecting bar 543 to the secondary feed arm 546 with its secondary overrunning feed clutch 558, providing as hereinbefore described, a primary and secondary dual type of feed, activated from a single source and each type of feed readily available by separate independent clutch assemblies either singly or jointly and with readily available separate means for raising or lowering the primary or secondary rack feed bars and their attendant label pack supports by separate hand cranks.

For purposes of providing the respective primary and secondary feed and rack bars 424 and 424' with suitable bearings for their vertical movements whereby the bars are guided by their respective bearings in a firm, stabilized manner and given a certain rigidity by their bearings, the depending brackets 501 and 502, rigidly supported on the underside of frame plate 428, are each provided with spaced upper and lower bushed bearings 613, 613' and 614, 614' respectively for the respective feed and rack bars 424 and 424'. Further, this spacing of the bearings allows for the actuating feed gears 503 and 504 respectively enmeshed with the rack bars 424 and 424' to be positioned between the said respective upper and lower bearings where there would be a minimum of spring in the rack bars due to the pressure of the feeding action between the said gears and rack bars.

Referring to FIGS. 6, 11, 16 and 17 and particularly 16 and 17 showing improved holding and adjusting means for a label hold down knife for removably holding the top labels down of the label pack in the initial label pickup area, as shown attached to the rear end face 615 of each of the label pack guides 387 positioned on each side of the machine and located under the upwardly inclined portion 399 of each of the can tracks 339. The present device comprises a single movable clamping jaw member 616 having a lower tongue portion 617 running throughout its width that has a sliding fit in the groove 618 formed in the face 615 of the label guide, forming a tongue and groove assembly for these parts. The upper portion of the clamp is somewhat offset from the tongue structure forming the jaw 619 of the clamp, the inner face of which impinges against the side face of the blade 620, the opposite face of the blade fits into a shallow undercut 621 formed in the face 615 the depth of which is less than the thickness of the blade, having an upper shoulder 622 against which the flat top of the blade has positioning and sliding engagement, with the bottom knife edge of the blade resting on the offset shoulder 623. The clamping member 616 is provided with a clamping screw 624, for exerting clamping pressure on the blade member, positioned in the screw hole 625 of the clamp and threadedly engaged to the label guide at 626 as shown. The depth of the groove 618 is sufficient to provide clearance at the underside 626 of the tongue portion after the blade has been placed in a clamped position to allow for additional tightening of screw 624 if necessary. The clamped blade is securely held in place and prevented from cocking by the upper and lower shoulders 622 and 623 respectively. Further the somewhat exposed blade with its engagement with a flat clamping surface is simpler to adjust and more efficient in operation and less costly to maintain.

With particular reference to FIGS. 6 and 28 the machine is also provided with a pair of the usual adjustable type of label hold down blades 627 having cylindrical shanks and positioned in the label guide brackets 342 with slide bearings therefor and set screws to fix the position of the blades therein. The blades being located in juxtaposition to the label curling bar 373 on each side 45 of the machine for engagement with and for removably retaining the top labels of the label pack.

Referring to FIGS. 7 and 12 the cans, after passing the paste belt station and final label wrap around operation, the cans with their fully wrapped around labels reach the ends 628, of the can tracks 392 and pass onto the label pressing pad 629, preferably made of sponge rubber, and being under pressure from the spring pressured conveyor belt 12, thence passing to the discharge plate 630 where the belt pressure is released, and then to the can discharge chute 631 as the final operation. The superimposed pressure by the single belt 12 on the center wall area of the labeled cans when being conveyed over the pad causes the reactive pressure of the pad surface on the label of the can to be applied over the whole label surface in the can rolling operation, which is particularly important as to the areas of the label where adhesives are identified. This operation together with the frictional action of the single belt on the labels and center wall of the cans tends to tighten the labels and prevents curling of the label ends at the label overlap areas.

The pad 629 may be attached to its supporting plate 632 by a suitable adhesive or the like with the plate being attached by screws as shown to the cross bars 633 which in turn are supported by the top frame bars 5 1 and 2' fixedly attached to the frame bars by screws 634. The discharge plate 630 is attached to both the end cross bar and pad supporting plate 632 by screws 635. The discharge plate is elevated to the plane of the pad by interposing a block between the pad plate 632 and the discharge plate 630 as shown.

FIGS. 47 to 53 disclose a glue pot 636 having modified means for applying glue to the walls of the passing cans together with a variable friction drive therefor all readily adaptable to the labeling machine as hereinbefore described. This glue pot 636 itself is similar in structure to the specific design of the glue pot 30 identified with the preferred form of described labeler. In this respect the modified means for applying the glue comprises a plurality of glue fountain fingers 636 positioned within the pot and swingingly mounted and positioned on their supporting shaft 638 in separate gangs 639 and 640, the shaft having a flat area 641 resiliently engaged by the fountains when in operative position. The shaft 638 having retaining collars 642 fixedly engaged to the shaft by set screws and between which the fountain fingers are positioned. Also mounted on the shaft between the respective fountain finger gangs is a gang separator sleeve 643. This sleeve as may be noted in FIG. 47 is positioned immediately under and slightly 20 beyond on each side of the container track or can runway 32, shown in fine dotted lines, to allow for clearance of the runway for the two inside fountains next to the ends of the sleeve, should it be found necessary to flip these fountains over for any reason to an inoperative position. It is understood the number of fountains to each gang may be varied to suit a given need. In the present assembly each gang comprises five fountain fingers and as shown in FIG. 47, the two outside or end fountains of each gang have been flipped over to an inoperative position, leaving three fountains effective for the glue pickup operation by the rolling can when passing over the small fountains of glue, flowing upward from each of the fountain orifices 644 formed in the fountainheads 644' of each fountain finger. With this fountain arrangement any combination of fountains such as every other one may be used to suit the need or to the width of the label or height of the can.

One end of the shaft 638 is adjustably fixedly and supported in the bearing 645 of the bearing bracket 50 646 by set screw 647, and the bearing bracket is held fast to the bosses at the bottom of the pot by screws 648. The opposite end of the shaft is positioned in the bearing 649 formed in the rear wall 650 of the glue pot. The pot is also provided with a glue pickup cylinder 55 651 that is power driven and constantly running under normal operating conditions in the heated glue in the pot. This cylinder is carried on the shaft 652 and fixedly positioned thereon by set screw 653 positioned in the cylinder hub 654. The shaft 652 is positioned and rotates in the bushed bearing 655 in the rear wall 650 of the pot. The cylinder shaft near its opposite end is rotatively mounted in the bracket bearing 657 with a shaft 60 positioning collar 658 located and affixed to the end of the shaft.

The underside glue cylinder contacting surface of each of the fountain fingers is arcual or curved as indicated at 659, with a radius substantially the same as

that of the outside cylindrical surface 660 of the glue pickup cylinder 651, whereby the underside cylinder contacting surface of the fountain fingers will conform, match and have substantially full contact with that of the glue pickup surface of the cylinder.

The underside of each fountain finger is provided with an under cut or slot 661 that terminates with a closed end slightly beyond the fountain glue orifice 644 in the form of a shoulder 662, with the opposite end 663 of the slot being open for the free entrance therein of glue near the pivotal end of the fountain finger. The bottom wall 664 of the slot is also curved like that of the outer surface of the cylinder wall with substantially the same radius as that of the cylinder outer surface plus the depth of the slot to provide a slot of uniform cross section for the free unimpeded flow of the glue up to the orifice 644. The upper portion 665 of the orifice is slightly smaller than the lower portion 666 of the orifice for purposes of causing a slight jet action to the glue as it leaves the orifice.

With particular reference to FIG. 49, the comparative semi-heavy viscosity of the glue as it is carried upward by the glue cylinder and into the slots 661 and thence being forced through the orifices 644, tends to lift the fountain fingers upward for various distances, depending on the density of viscosity of the glue and the speed of rotation of the cylinder and further the thickness of glue on the cylinder throughout its length is not uniform, therefor the lifting of the fountain fingers is not uniform causing variables in the distances of the various fountain heads 644' from the underside of the overrunning cans with variables on the heights of the glue jets without uniform application of fountain glue to the cans from the different jets of glue.

To correct this and to produce uniform heights to the glue jets with substantially uniform distances of the various fountain heads from the underside of the overrunning cans and for more uniform application and glue pickup by the cans, each of the fountain fingers is provided with a spring loaded ball 667 positioned partly within the end coils 668 of the compression spring 669 therefor, the opposite end of which is compressed against and engages the inner end wall 670 of the blind hole 671 that houses and positions the ball and spring assembly within the fountain finger. Each of the balls impinge under spring pressure against the flat surface 672 of the rotatably adjustable supporting shaft 638 therefor. The fountain fingers are each provided with bearing openings 673 through which the shaft passes and for rotatably supporting them on the shaft. The shaft flat area 672 extends in a continuous manner slightly beyond each of the end collars 642 as shown. As noted in FIG. 49 the plane of the flat is normal to the longitudinal axis of the spring and ball assembly and this axis bisects the shaft axis and is substantially tangent to the outer curve of the glue cylinder when in a substantially normal neutral position as shown. By loosening set screw 647 the shaft with its flat may be reset by rotating the shaft slightly clockwise and retightening the set screw, causing the flat by its changed angle to move all the balls back simultaneously and in a unified manner, slightly compressing all the spring members and thus causing the fountain fingers to hold against the rotating glue covered cylinder surface under proportionate spring pressure to prevent the fingers from lifting or floating above the cylinder surface due to the rotating action of the cylinder the degree of viscosity of

the glue and the speed of rotation of the cylinder whereby substantially all the glue that enters the slot will be delivered from the jet orifice 644. Under certain operating conditions of variables of the above conditions it may be desirable to neutralize the spring setting to allow the fountain fingers to contact the glue laden rotating cylinder with substantially little or no spring pressure but with sufficient spring reaction to set up spring resistance against the fountain fingers moving 10 away from the cylinder. The height of the glue fountain after it leaves the orifice 644 is approximately three-sixteenths inch, as it is only necessary for the side walls of the passing cans to barely touch the tops of the jets of glue formed by and emanating from the glue orifices 644. This result may be accomplished by setting the flat 641 to the position shown in FIG. 49.

As this type of glue applicator is sensitive to varying operating or driving speeds it is advisable to have separate driving means for controlling the rotating speed of 20 the glue cylinder interposed between the main drive for the labelling machine as a whole and the present modified form of glue pot. The present glue pot proper 636 with its modified form of glue applicator, is like the preferred form structurally and is readily adaptable to all 25 the structural elements identified with the preferred form such as the heater, supporting brackets identified with the adjustment of the glue pot on the supporting racks except the modified drive for the glue cylinder which is somewhat different from the described preferred form but readily adaptable to the structural features of the present labeler as shown and described without the necessity of changes except the removal of the preferred form of glue pot and its specific drive connections to the longitudinal drive shaft 263 of the 30 labeling machine proper.

It is understood the present modified form of glue pot with its fountain fingers may be readily adapted to be 35 driven by the same drive as that used for the preferred form of glue pot without the intervening variable drive to be hereinafter described.

The present modified drive is of the variable speed 40 friction type and provides means whereby the speed of the glue cylinder 651 may be varied independently of the operating speed of the labeler and its drive. This 45 separate speed drive is important in the present instance in view of the above description relating to glue viscosity, adaptation of fountain finger pressure on the cylinder and adaption of cylinder speed to glue viscosity in relation to the operating speed of the labeling machine.

With particular reference to FIGS. 50 to 53 the glue cylinder drive shaft 652 extends beyond the rear face of the glue pot and has fixedly mounted thereon gear 674 that is enmeshed with and driven by gear 675 fixedly mounted on one end of the driven shaft 676 supported in bracket bearing 677 which is an integral part of the glue pot bracket member 675 fastened to the rear face of the glue pot by screws 679. The opposite end of shaft 676 has fixedly mounted thereon by 50 screw 680 a friction driven disc 681. The screw head is welded at 682 to the face of the disc to prevent the disc turning in relation to the screw. The opposite face of the disc bears against a thrust bearing 683 carried on the shaft, which in turn bears against one end of a compression spring 684, the opposite end of which bears against the bearing face 685. The bearing bushing 686 of bearing 677 extends out from the bearing face 685

for about two-thirds the width of the bearing, providing a supporting guide for the spring 684 with clearance space between its end and the thrust bearing 683 to allow for yielding action of the disc 681, with the clearance space 687 between the gear 675 and bearing 677 also being for the same purpose. These clearance spaces allow for sliding and yielding movement of the shaft and disc respectively in relation to the driving head 688 and to compensate for wear of the driving head.

The friction driven disc 681 has spring loaded engagement with the rotating driving head 688 and being driven by and having keyed and sliding engagement with the elongated rotating drive shaft 263 and its elongated keyway 264. The driving head 688 is provided with a disc contacting friction ring 689 having high friction characteristics to prevent slippage and may be made of a suitable fibrous material. A thrust bearing 690 is provided between the rotating head and the positioning fork 691 that engages the grooved portion of the collar 692 for causing the head to be moved along the drive shaft 263 when the glue pot is moved to various adjusted positions for different length labels. This driving head moving fork 691 is part of an adjustable bracket 693 having a pair of screws 694 positioned in adjusting slot 695 of the glue pot bracket 678 for maintaining the fork and drive head in fixed adjusted position in slot 695. By sliding the bracket 693 and its screws along the adjusting slot 695 causes the friction ring 689 to be moved toward or away from the disc center to change the ratio of speed between the elongated drive shaft 263 of the labeling machine and the driven speed of the glue pot cylinder 651 whereby the cylinder speed may be either increased or decreased independently of the speed ratio of the labeler drive shaft 263.

I have thus described a machine embodying my invention in its preferred form, including a modified form of glue applicator for the glue pot with its driving means, the description being specific and in detail in order that the manner of constructing, applying, operating and using the invention may be fully understood, however, while the preferred form and the modified form of glue pot and drive has been described specifically and in detail, numerous variations and changes of design are contemplated within the spirit of this disclosure and the specific terms herein are used in a descriptive rather than in a limiting sense, the scope of the invention being defined in the claims.

What I claim as new and desire to secure by Letters Patent is:

1. In a can labeling machine having a substantially horizontal runway for supporting cans, means for supporting a pack of labels, comprising primary and secondary label pack supporting and feeding means, means extending over the runway for feeding the cans over the labels of the pack, means for applying glue to the cans to cause the cans to initially pick up the labels when passing over the label pack, the secondary label pack supporting and feeding means comprising of pair of pivotally supported and downwardly yielding, horizontally extending arms, each having a plurality of label pack supporting members adjustably attached thereto, the outer ends of the arms being free with their opposite ends having engagement with abutment means, to prevent the arms from swinging upward, the pivotally supported ends comprising downwardly directed arms

having at their ends and in engagement with means for applying predetermined outwardly directed spring pressure against the ends of the downwardly directed arms for purposes of providing yielding action to the horizontal arms when supporting a label pack, means for pivotally supporting each pair of horizontal and downwardly directed arms comprising a complementary pair of transverse sliding brackets, each having upper and lower bearings for bearing and sliding engagement with a pair of complementary upper and lower transverse supporting bars therefor, the brackets being in lateral spaced relation to each other, means for feeding the secondary label pack supporting means comprising a toothed rack bar fixedly carrying at its upper end a bracket having fixed engagement with both the upper and lower transverse supporting bars for the pair of transverse sliding brackets mounted thereon, end guide bars for the label pack at the label pickup end of the pack, attached at their respective upper ends to screw follower brackets threadedly engaged to right and left hand threaded halves respectively of a transverse adjustable screw members, means fixedly attached to each of the screw follower brackets and slidably engaged vertically with the transverse sliding brackets for simultaneously moving the secondary label pack supporting arms and the said end guide bars for the label pack in a lateral direction and for a distance suitable for supporting and guiding a label pack of a particular width upon turning the transverse adjustable screw member, the said feeding means including a rotatable shaft for operating the label supporting means relative to the said runway, an oscillatable overrunning clutch for rotating said shaft, and a stationary over-running clutch positioned in the opposite direction on said shaft for preventing backlash of said shaft.

2. In a can labeling machine having a runway for supporting the cans, a feed belt movable over runway for feeding the cans through the machine, means for supporting and guiding the cans while being fed through the machine comprising, means for picking up labels by the cans and means for applying the labels to the cans as they are fed through the machine, a label table for supporting a pack of labels, means for feeding the label table and labels towards the ways for replenishing the top labels as they are consumed by the passing cans comprising an oscillating overrunning feed clutch and a non-oscillating, non-feeding over-running shaft locking clutch positioned on the same shaft with the oscillating overrunning feed clutch having means to prevent backward rotation of the feed shaft, means for engaging and disengaging means for oscillating the overrunning feed clutch from the driven portions of the machine, means for starting the feeding oscillations of the overrunning feed clutch and also starting the feeding movement of the label table when there is a need for more labels to be moved up to a pickup position for the cans, being fed through the machine means for stopping the oscillations and the feeding movement of the label table when the need has been satisfied, comprising spring actuated depressable means positioned in the path of the passing cans, means for moving the depressable means down for a predetermined distance as the labels are consumed for releasing the engaging means for starting the oscillations of the overrunning feed clutch to feed the label table with its label pack upward sufficiently to substantially replace the consumed labels, spring actuated means for returning the depress-

able means to normal raised position upon the replacement of the said consumed labels with means for stopping the feeding oscillations of the overrunning feed-clutch and the feeding movement of the label table.

3. In a can labeling machine having a runway for supporting cans, a feed belt for feeding cans through the machine, means for guiding the cans, comprising means for supporting and feeding the labels comprising a primary support and feed for a label pack consisting of a label table and a secondary support and feed for the label pack comprising a pair of yieldingly supported extending arms having label pack engaging and supporting means positioned on the arms, the primary and secondary feed means comprising a hand operated clutch for each of the feeds, means for actuating the feeding function of either the primary or secondary label supports comprising feed control spring actuated members positioned in the path of the cans, normally held in raised non-feeding position and providing means for starting the upward feeding of the labels by either the primary or secondary supports upon contact by the overrunning cans being fed through the machine causing the feed control members to be depressed sufficiently to release a feed locking means for both the primary and secondary feed, means whereby upon operative engagement of either of the said respective hand clutches that respective primary or secondary label support will be fed upward that is identified with the respective engaged hand clutch, means for and whereby upon the effective replacement of previously consumed labels by either the primary or secondary feed action causing an increase in the height of the label pack in the path of the cans, the cans are prevented from bearing down on the said spring actuated feed control members allowing these members to return to their original raised position, said raised position of the members providing means for reengagement of the feed locking means for both the primary and secondary feed and stopping the respective feeding action of either the primary or secondary respective feed that is in engaged feeding position with its respective hand operated clutch.

4. In a can labeling machine having a feed belt for feeding cans through the machine, means for supporting, guiding and labeling the cans as they pass through the machine comprising power driven label feeding means for intermittently feeding labels into the path of the cans comprising label pack supporting means, can

actuated depressable means positioned in the path of the cans and along the can supporting means over which the cans travel and having raised and lowered positions, with means for being returned from lowered to raised position, the depressable means starting the label feeding means upon the depressable means being depressed to a given point by the cans and depletion of the labels and stopping the label feeding means upon the said depressable means rising to its original raised position upon the instant demand for more labels being satisfied, and the label feeding means comprising primary and secondary label pack feeding means including a rotatable shaft for operating the label supporting means relative to the can supporting means, an oscillatable over-running clutch for rotating said shaft and a stationary over-running clutch positioned in the opposite direction on said shaft for preventing backlash thereof.

5. In a can labeling machine having a feed belt for feeding cans through the machine, means for supporting, guiding and labeling the cans as they pass through the machine comprising, power driven label feeding means for intermittently feeding labels into the path of the cans comprising label pack supporting means, can actuated depressable means positioned in the path of the cans and over which the cans travel and having raised and lowered positions, with means for being returned from lowered to raised position, the depressable means starting the label feeding means upon the depressable means being depressed to a given point by the cans and depletion of the labels and stopping the label feeding means upon the said depressable means rising to its original raised position upon the instant demand for more labels being satisfied, the said label feeding means comprising primary and secondary label feed assemblies actuated and controlled by the said depressable means, each of said assembly having rack and pinion members for actuating the feeding function of the said label pack supporting means, each pinion fixed to separate shafts, each of the shafts having a pair of overrunning clutches, one of said clutches of each pair being operable and means for operating said clutch and the other over-running clutch of each pair of clutches being stationary and in reversed position on said shaft for preventing backlash of the respective shafts.
